RAILWAY SIGNALING SYSTEM

Paul H. Crago, Wilkinsburg, Pa., assignor to The
Union Switch & Signal Company, Swissvale,
Pa., a corporation of Pennsylvania

Application June 10, 1936, Serial No. 84,498
Renewed June 24, 1938

42 Claims. (Cl. 246—46)

My invention relates to railway signaling systems of the type involving light signals which are approach lighted.

One object of my invention is to provide novel means for causing an approach lighted signal to display a restrictive indication when a train approaches the signal if the filament of the lamp for the signal next in advance becomes burned out or broken.

10 Other objects of my invention will appear as the description proceeds.

The railway signaling system set forth in my present application is somewhat similar to that set forth in the copending application of Henry S.

15 Young, Serial No. 742,095, filed on August 30, 1934, for Railway signaling system, and the said copending application contains claims which cover broadly certain features of the invention described in my present application.

20 I will describe several forms of railway signaling systems embodying my invention, and will then point out the novel features thereof in claims.

In the accompanying drawings, Fig. 1 is a diagrammatic view showing one form of signaling system embodying my invention. Fig. 2 is a diagrammatic view showing a modification of the signaling system illustrated in Fig. 1. Figs. 3 and 3^a are diagrammatic views which, when placed 25 end to end with Fig. 3^a on the right, show still another form of signaling system embodying my invention. Fig. 4 is a diagrammatic view showing a modification of the signaling system illustrated in Figs. 3 and 3^a. Figs. 5 and 5^a are diagrammatic views which, when placed end to end with Fig. 5^a on the right, show still another form of signaling system embodying my invention. Figs. 6 and 6^a are diagrammatic views which, when placed end to end with Fig. 6^a on the right, 30 show still another form of signaling system embodying my invention. Fig. 7 is a diagrammatic view showing a modification of the signaling system illustrated in Figs. 6 and 6^a.

Similar reference characters refer to similar 45 parts in each of the several views.

Referring first to Fig. 1, the reference characters 1 and 1^a designate the track rails of a stretch of railway track along which traffic normally moves in the direction indicated by the arrow. 50 These track rails are divided, by means of insulated joints 2, to form blocks, only one of which, A—B, is shown complete in the drawings. Each block is provided with a track circuit comprising a track relay, designated by the reference character TR with a suitable distinguishing exponent,

and connected across the rails adjacent one end of the section, and a suitable source of track circuit current, here shown as a track battery 3, connected across the rails adjacent the other end of the section.

5 Located adjacent the entrance end of each block is a signal designated by the reference character S with an exponent corresponding to the location. Each signal, as here shown, is of the type commonly known as a searchlight signal, and comprises an armature 5 mounted to rotate between an intermediate position to which it is biased, and two extreme positions. Each armature 5 is controlled by an armature winding 6, and is polarized by the field from a permanent 10 magnet or an electromagnet (not shown) in such manner that when the winding 6 is energized, the armature will rotate to its right-hand or left-hand extreme position according as winding 6 is then supplied with current of normal or reverse 15 polarity, respectively. Attached to each armature 5 to rotate therewith are three colored roundels G, R, and Y, which are arranged to be disposed in the path of a beam of light projected from an associated lamp L according as the armature 5 20 occupies its right-hand extreme position, its intermediate position, or its left-hand extreme position, respectively. For convenience in illustration, each lamp L in the drawings is shown disposed above the associated roundels, but it will be 25 readily understood that in actual practice each lamp will be located directly back of the associated roundel, and will have associated therewith a suitable optical system, not shown, for projecting 30 a beam of light from the lamp. The signals 35 S each indicate "proceed", "stop", or "caution" according as the roundel G, R, or Y is in front of the associated lamp L when this lamp is lighted. Operatively connected with each armature 5 is a 40 circuit controller comprising two movable contact fingers 7 and 8. The movable contact finger 7 cooperates with a fixed contact 7^a to close a contact 7—7^a when the armature 5 occupies its right-hand extreme position, and with a fixed contact 45 7^b to close a contact 7—7^b when the armature occupies its intermediate position or its left-hand extreme position; while the movable contact finger 8 cooperates with a fixed contact 8^a to close a contact 8—8^a when the armature occupies its 50 left-hand extreme position, and with a fixed contact 8^b to close a contact 8—8^b when the armature occupies its intermediate or its right-hand extreme position.

A signal of the type described is disclosed and claimed in Letters Patent of the 55

United States No. 1,864,224, granted to Wesley B. Wells, on June 21, 1932, for Light signal.

Associated with each signal is a slow-releasing signal repeater relay designated by the reference character SR with a suitable distinguishing exponent, an approach lighting relay designated by the reference character ALR with a suitable distinguishing exponent, and a slow-releasing lightout relay designated by the reference character LOR with a suitable distinguishing exponent. Each lightout relay LOR is provided with two windings, one of which, 9, has a sufficiently high resistance so that when this winding is connected in series with the filament of the lamp L of the associated signal in a checking circuit for the lamp presently to be described, the lamp will not become lighted, and the other of which, 10, has a sufficiently low resistance so that when this winding is connected in series with the filament of the lamp L of the associated signal in an energizing circuit for the lamp presently to be described, the lamp will become lighted.

Each signal repeater relay is provided with two energizing circuits which are controlled by the circuit controller of the associated signal. Referring to relay SR^A, for example, the one energizing circuit for this relay is closed when and only when signal S^A indicates proceed, and passes from terminal X of a suitable source of current not shown in the drawings through contact 7-7^a of signal S^A, wires 24 and 25, and the winding of relay SR^A to terminal O. The other energizing circuit for relay SR^A is closed when and only when signal S^A indicates caution, and passes from terminal X through contact 7-7^b of signal S^A, wire 32, contact 8-8^a of signal S^A, wire 25, and the winding of relay SR^A to terminal O. It will be apparent, therefore, that relay SR^A will be energized when signal S^A occupies either its proceed or its caution position, but will be deenergized when signal S^A occupies its stop position. Relay SR^A is made sufficiently slow releasing so that it will not open its front contacts while signal S^A is moving from its proceed to its caution position, or vice-versa.

The winding 6 of each signal is controlled by the associated track and lightout relays and by the signal repeater relay for the signal next in advance, through the medium of a polarized line circuit which includes the winding of the approach lighting relay for the signal next in advance. Referring to signal S^A, for example, when track relay TR^A and lightout relay LOR^A are both energized, and signal repeater relay SR^B is also energized, the polarized line circuit for winding 6 of signal S^A is closed, and under these conditions, winding 6 is supplied with current of normal polarity, the path of the current being from terminal X through the winding of relay ALR^B, wire 12, front contact 13-13^a of relay SR^B, line wire 14, front contact 15 of track relay TR^A, wire 16, front contact 17 of lightout relay LOR^A, wire 18, winding 6 of signal S^A, wire 19, front contact 20 of track relay TR^A, line wire 21, front contact 22-22^a of signal repeater relay SR^B, and wire 23 to terminal O. When track relay TR^A and lightout relay LOR^A are both energized and signal repeater relay SR^B is deenergized, the polarized line circuit for winding 6 of signal S^A is again closed, but under these conditions, due to the fact that the back contacts 13-13^b and 22-22^b of relay SR^B are then closed instead of the front contacts 13-13^a and 22-22^a, winding 6 of signal S^A is supplied with current of reverse polarity over this line circuit. When either track relay

TR^A or lightout relay LOR^A is deenergized, the polarized line circuit for winding 6 of signal S^A will, of course, be open.

It will be apparent, therefore, that when track relay TR^A and lightout relay LOR^A are both energized, the mechanism of signal S^A will occupy its proceed or its caution position according as signal repeater relay SR^B is then energized or deenergized, but that, when either track relay TR^A or lightout relay LOR^A is deenergized, the mechanism of signal S^A will occupy its stop position. It will also be apparent that approach lighting relay ALR^B will be energized whenever winding 6 of signal S^A is energized by current of either normal or reverse polarity, but that, when winding 6 of signal S^A is deenergized, approach lighting relay ALR^B will also be deenergized.

Each signal lamp L is provided with an energizing circuit which is controlled by the associated signal repeater and approach lighting relays in such manner that this circuit will become closed when either of these relays becomes deenergized, and which includes the low resistance winding 10 of the associated lightout relay. Each signal lamp L is also provided with a checking circuit which includes the high resistance winding 9 of the associated lightout relay, and which is closed at all times except when the lamp filament becomes broken or burned out. Referring particularly to lamp L^A of signal S^A, the energizing circuit for this lamp passes from terminal X through the filament of lamp L^A, wires 26 and 27, back contact 28 of relay SR^A connected in multiple with back contact 29 of relay ALR^A, wire 30, winding 10 of relay LOR^A, and wire 31 to terminal O. The checking circuit for lamp L^A passes from terminal X through the filament of lamp L^A, wire 26, resistor R^A, and the winding 9 of lightout relay LOR^A to terminal O. The parts are so proportioned that lamp L^A will become lighted when and only when the energizing circuit for the lamp is closed, but that, relay LOR^A will hold its front contacts closed when either the energizing or the checking circuit for lamp L^A is closed.

It should be pointed out that while, as shown in the drawings, each checking circuit includes a resistance R, this resistance can be omitted if the resistance of the high resistance winding is sufficiently high to prevent the filament of the associated lamp from becoming incandescent while the checking circuit in which the resistance is included is closed and the associated energizing circuit is open. It should also be pointed out that when the energizing circuit for a lamp is closed, the checking circuit is also closed, so that the current which is supplied to the lamp flows through the windings 9 and 10 of the associated lightout relay in parallel. The windings 9 and 10 are so arranged that the fluxes set up in the relay when both of these windings are energized are cumulative.

As shown in the drawings, all parts are in their normal positions, that is to say, all relays are picked up, the winding 6 of each signal is supplied with current of normal polarity, so that the armatures 5 of signals S^A and S^B both occupy their right-hand or proceed positions, and the lamps L^A and L^B are both extinguished.

In explaining the operation of the apparatus as a whole, I will first assume that a train moving in the direction of the arrow traverses the stretch of track shown in the drawings. When the train enters the block in rear of block A-B,

the shunting of the track relay associated with this block will cause approach lighting relay ALR^A to become deenergized and close its back contact 29. The closing of this contact will complete the energizing circuit for lamp L^A , and this lamp will therefore become lighted and will cause signal S^A to display a proceed indication. 5

When the train enters block A—B, track relay TR^A will become deenergized, and will interrupt the circuit for winding 6 of signal S^A , thus causing the mechanism of this signal to move to its stop position, and approach lighting relay ALR^B to become deenergized. When signal S^A moves to its stop position, it will interrupt the circuit which was previously closed for signal repeater relay SR^A , and since both circuits for this relay will then be open, this relay will become deenergized. The deenergization of relay SR^A will cause the polarity of the current supplied to the circuit for the winding 6 of the signal for the block to the right of block A—B to become closed, and as a result, as soon as the train moves out of this block, this signal will move to its caution position. The deenergization of relay SR^A will also cause this relay to complete, at its back contact 28, the energizing circuit for lamp L^A including this contact, so that when the approach lighting relay ALR^A picks up due to the train having passed out of the block to the right of block A—B, signal S^A will continue to display a stop indication. The deenergization of approach lighting relay ALR^B will cause the energizing circuit for lamp L^B of signal S^B to become closed, and this lamp will therefore become lighted, thus causing signal S^B to display a proceed indication. 30

When the train enters the block to the left of block A—B, track relay TR^B will become deenergized and will cause winding 6 of signal S^B to become deenergized. The deenergization of winding 6 of signal S^B will cause the mechanism of this signal to move to its stop position, which movement, in turn, due to the resultant operation of the associated circuit controller, will de- 45 energize signal repeater relay SR^B . When relay SR^B becomes deenergized, it will reverse the polarity of the current supplied to the circuit for winding 6 of signal S^A , but as long as any part of the train remains in block A—B, the circuit for winding 6 will remain open at the front contacts of track relay TR^A , and signal S^A will continue to display a stop indication. As soon, however, as the train passes completely out of block A—B, the resultant energization of track 50 relay TR^A will complete the circuit for winding 6 of signal S^A , and this signal will then move to its caution position. The movement of signal S^A to its caution position will complete the previously traced circuit for signal repeater relay SR^A including contacts 7—7^b and 8—8^a of the circuit controller of signal S^A , and relay SR^A will then pick up. When this relay picks up, it will interrupt the energizing circuit for lamp L^A , and will cause the winding 6 of the signal for the block to the left of block A—B to be supplied with current of normal polarity, whereupon the mechanism of this signal will move to its proceed position. 55

When the train leaves the block to the left of block A—B, track relay TR^B will pick up and will cause signal S^B to move to its caution position in the same manner that the picking up of track relay TR^A caused signal S^A to move to its caution position. As soon as signal S^B reaches its caution position, signal repeater relay SR^B will pick up, whereupon signal lamp L^B will become extinguished, and the mechanism for signal S^A will move to its proceed position. When the train passes out of the second block in advance of block A—B, signal S^B will move to its proceed position, and all parts will then be restored to the positions in which they are shown in the drawings. 60

I will now assume that with the parts in the positions in which they are shown in the drawings, 10 the filament of lamp L^B becomes broken, and that a train subsequently enters the block to the right of point A. When the filament of lamp L^B becomes broken, the checking circuit for this lamp becomes interrupted at the lamp filament, 15 and lightout relay LOR^B therefore becomes deenergized, and opens its front contact 11. The opening of this front contact will deenergize the winding 6 of signal S^B , whereupon the signal mechanism of this signal will move to its stop 20 position. When the mechanism of signal S^B moves to its stop position, signal repeater relay SR^B will become deenergized, and will reverse the polarity of the current supplied to winding 6 of signal S^A , thus causing the mechanism of 25 signal S^A to move to its caution position. As a result, when the train enters the block to the right of point A and causes approach lighting relay ALR^A to become deenergized and complete the circuit for lamp L^A , signal S^A will indicate 30 caution even though neither of the two blocks in advance of point A is occupied.

If signal S^B occupies its caution position instead of its proceed position when the filament of lamp L^B becomes broken, and a train subsequently enters the block to the right of point A, the operation of the apparatus will be similar in all respects to that just described. It will be seen, therefore, that with a signal system constructed in the manner described, if the filament of a 40 signal lamp becomes broken when the mechanism of the signal in the rear occupies its proceed position, the mechanism of the signal in the rear will immediately move to its caution position, thus insuring that an engineman will not be required to pass a signal which indicates proceed, 45 only to find the signal next in advance dark. Since the operating rules of railroads usually require that a dark signal be obeyed as a stop signal, the arrangement herein disclosed aids in 50 removing the operating hazard of a sudden brake application resulting from an unexpected dark signal.

If the lamp of a signal burns out after it has become lighted due to the presence of a train in the block immediately in rear of the signal, both the checking and energizing circuits for the lamp will become open, and the associated lightout relay will become deenergized, and will thus cause the signal mechanism to move to its stop 55 position. This is desirable because since the operating rules of railroads usually require that a dark signal be obeyed as a stop signal, and since the signal mechanism occupies its stop position, if any light from an extraneous source such, for example, as a locomotive headlight or the sun's rays when the sun is close to the horizon, should enter the signal and be reflected back by the optical assembly of the signal, the resulting phantom indication would be a stop indication. 60 The signal mechanism, after being moved to its stop position in the manner just described, will subsequently remain in its stop position until the burned out lamp is replaced, and the signal next in rear will be prevented from moving to 65 70 75

its proceed position, even though traffic conditions in advance are such that the mechanism of this signal would normally assume its proceed position.

- 5 Referring now to Fig. 2, in the modified form of the apparatus here illustrated, there is provided at each signal location, in addition to the apparatus shown in Fig. 1, a transformer designated by the reference character T with a suitable distinguishing exponent, a "power-off" relay designated by the reference character POR with a suitable distinguishing exponent, and a standby or reserve source of power here shown as a battery designated by the reference character E with a distinguishing exponent. The primary winding 35 of each transformer T is constantly connected with the terminals Z and O of a suitable source of alternating current, not shown in the drawings, while the secondary winding 36 of each transformer T is constantly connected with the winding of the associated power-off relay. It will be seen, therefore, that each power-off relay will be energized at all times except in the event that the alternating current supply fails.
- 10 Each signal lamp L, as shown in Fig. 2, is provided with an energizing circuit which is closed when and only when the associated approach lighting relay ALR is deenergized and the associated signal repeater relay SR is energized, and with another energizing circuit which is closed whenever the associated signal repeater relay is deenergized regardless of whether the associated approach lighting relay is then energized or deenergized. Each of these energizing circuits includes the low resistance winding 10 of the associated light-out relay connected in multiple with a rectifier P, and is arranged to be supplied with either alternating current from the secondary winding 36 of the associated transformer T, or with direct current from the associated battery E, according as the associated power-off relay POR is then energized or deenergized. Referring particularly to lamp L^B, the one energizing circuit for this lamp normally passes from the right-hand terminal of transformer T^B through wire 37, front contact 38-38^a of power-off relay POR^B, wires 39 and 40, back contact 29-29^b of approach lighting relay ALR^B, wire 41, front contact 42-42^a of signal repeater relay SR^B, wire 43, low resistance winding 10 of light-out relay LOR^B connected in multiple with rectifier P^B, wire 44, the filament of lamp L^B, wires 45 and 46, front contact 47-47^a of power-off relay POR^B, and wire 48 to the left-hand terminal of transformer T^B; while the other energizing circuit for this lamp normally passes from the right-hand terminal of transformer T^B through wire 37, front contact 38-38^a of power-off relay POR^B, wires 39 and 49, back contact 42-42^b of signal repeater relay SR^B, wire 43, the low resistance winding 10 of light-out relay LOR^B connected in multiple with asymmetric unit P^B, wire 44, the filament of lamp L^B, wires 45 and 46, front contact 47-47^a of power-off relay POR^B, and wire 48 to the other terminal of transformer T^B. When power-off relay POR^B becomes deenergized due to a power failure, each of the energizing circuits just traced includes battery E^B and back contacts 38-38^b and 41-47^b of power-off relay POR^B in place of secondary winding 36 of transformer T^B, wires 37 and 48, and front contacts 38-38^a and 47-47^a of transformer T^B.
- 70 The function of the rectifier P^B in each of the circuits just traced is to enable the relay LOR^B

to be of the direct current type, and at the same time cause it to become energized whenever either of the energizing circuits for lamp L^B are supplied with alternating current from the secondary winding 36 of transformer T^B. The rectifier P^B also acts to render the relay slow releasing, which fact greatly facilitates the operation of the relay when the relay is supplied with alternating current.

Each signal lamp L, as shown in Fig. 2, is also provided with a checking circuit which is closed when and only when the associated approach lighting and signal repeater relays are both energized, and which includes both the low and high resistance windings of the associated lightout relay connected in series. Referring particularly to lamp L^B, the checking circuit for this lamp passes from terminal X through the high resistance winding 9 of relay LOR^B, wire 50, front contact 29-29^a of approach lighting relay ALR^B, 20 wire 41, front contact 42-42^a of signal repeater relay SR^B, wire 43, the low resistance winding 10 of lightout relay LOR^B connected in multiple with asymmetric unit P^B, wire 44, the filament of lamp L^B, and wire 45 to terminal O of the source. 25 The parts are so proportioned that when this circuit is closed, relay LOR^B will hold its front contact 47 closed but that, the filament of lamp L^B will remain dark.

The remainder of the apparatus shown in Fig. 2 30 is similar in all respects to the corresponding apparatus shown in Fig. 1.

With the system modified in the manner shown in Fig. 2, it will be noted that the energizing circuit for each signal lamp including the back 35 contact 29-29^b of the associated approach lighting relay and the front contact 42-42^a of the associated signal repeater relay will be closed when the block next in rear of the signal is occupied and the block next in advance is unoccupied, 40 and that, the other energizing circuit for each lamp will be closed whenever the block next in advance of the signal is occupied. It will be apparent, therefore, that each signal lamp will normally become lighted when a train enters the 45 block next in rear of the signal, and will subsequently remain lighted until the train passes completely out of the block next in advance of the signal. It will also be noted that with the system constructed in the manner shown in Fig. 2, when 50 the block next in rear and the block next in advance of a signal are both unoccupied, the checking circuit for the associated lamp will be closed if the lamp filament is then intact, but that, if the lamp filament is burned out, this 55 checking circuit will then be open. As was pointed out hereinbefore, each lightout relay will hold its front contacts closed when either of the two energizing circuits or the checking circuit for the associated lamp is closed, but will open its front contact when all of these circuits are open, and it will be seen, therefore, that the apparatus illustrated in Fig. 2 will function in the same manner as the apparatus illustrated in Fig. 1 60 when a lamp filament becomes broken or burns out. The operation of the portion of the apparatus shown in Fig. 2 but not specifically described, is the same as the operation of the corresponding apparatus shown in Fig. 1, and it is 65 believed to be unnecessary, therefore, to repeat the description of the operation of this portion of the apparatus.

Referring now to Figs. 3 and 3^a, the track rails 1 and 1^a, as here illustrated, are divided into 70

blocks in the same manner as in the preceding views, three such blocks A—B, B—C, and C—D, being shown complete in the drawings. Each of these blocks is provided with a track circuit including a track battery 3 and a track relay TR. Located at the entrance end of each block is a signal designated by the reference character S with a distinguishing exponent, each of which signals, as here shown, comprises two separate signal mechanisms each designated by the same reference character as the reference character for the associated signal with a distinguishing subscript. Each of these signal mechanisms is similar in all respects to the mechanism of the signals previously described, and in actual practice both mechanisms will usually be secured to the same pole or mast with the one mechanism disposed above the other mechanism. With this arrangement, when both mechanisms are displaying a red aspect, the signal indicates "stop"; when the upper mechanism displays a yellow aspect and the lower mechanism displays a red aspect, the signal indicates "caution"; when the upper mechanism displays a yellow aspect and the lower mechanism a green aspect, the signal indicates "approach restricting"; and when the upper mechanism displays a green aspect and the lower mechanism a red aspect, the signal indicates "proceed".

Associated with each signal are a polarized distant relay designated by the reference character DR with a distinguishing exponent, an approach lighting relay designated by the reference character ALR with a distinguishing exponent, a lightout relay designated by the reference character LOR with a distinguishing exponent, a slow-releasing repeater relay designated by the reference character SR with a distinguishing exponent, a power-off relay designated by the reference character POR with a distinguishing exponent, a transformer designated by the reference character T with a distinguishing exponent, a standby battery designated by the reference character E with a distinguishing exponent, and a reactor designated by the reference character F with a distinguishing exponent. Each reactor F has the same reactance as the low resistance winding 10 of the associated lightout relay for a reason which will become apparent as the description proceeds.

The energization of the winding 6 of each signal mechanism S₁ is controlled by the associated distant relay DR and by the associated track relay TR. Referring particularly to the winding 6 of signal mechanism S₁^A, when track relay TR^A is energized and distant relay DR^A is energized in its normal direction so that its polar contacts are swung toward the left, as shown in the drawings, this winding is supplied with current of normal polarity over a circuit which passes from terminal X through front contact 55 of track relay TR^A, wires 56 and 57, normal polar contact 58—58^a of distant relay DR^A, wire 59, front contact 60—60^a of distant relay DR^A, winding 6 of signal mechanism S₁^A, front contact 61—61^a of distant relay DR^A, wire 62, normal polar contact 63—63^a of distant relay DR^A, wires 64 and 65, and front contact 66 of track relay TR^A to terminal O. When, however, track relay TR^A is energized and distant relay DR^A is energized in its reverse direction so that its polar contacts are swung toward the right, winding 6 of signal mechanism S₁^A is then supplied with current of reverse polarity over a circuit which passes from terminal X

through front contact 55 of track relay TR^A, wires 56 and 57, reverse polar contact 63—63^b of distant relay DR^A, wire 62, front contact 61—61^a of distant relay DR^A, winding 6 of signal mechanism S₁^A, front contact 60—60^a of distant relay DR^A, wire 59, reverse polar contact 58—58^b of distant relay DR^A, wires 61, 68, 64 and 65, and front contact 66 of track relay TR^A to terminal O. When track relay TR^A is energized and distant relay DR^A is deenergized, winding 6 of signal mechanism S₁^A is then supplied with current of reverse polarity over a circuit which passes from terminal X through front contact 55 of track relay TR^A, wire 56, back contact 61—61^b of distant relay DR^A, winding 6 of signal mechanism S₁^A, back contact 60—60^b of distant relay DR^A, wire 65, and front contact 66 of track relay TR^A to terminal O. When winding 6 of signal mechanism S₁^A is supplied with current of normal polarity this signal mechanism will, of course, occupy the position in which the green roundel G is disposed in front of the associated lamp L, and when winding 6 of this signal mechanism is supplied with current of reverse polarity, this signal mechanism will occupy the position in which the yellow roundel Y is disposed in front of the associated lamp L.

The winding 6 of each signal mechanism S₂ is controlled by the associated distant relay DR, by the associated track relay TR, by the associated lightout relay LOR, and by the circuit controller of the associated signal mechanism S₁. Referring particularly to winding 6 of signal mechanism S₁^B, this winding is provided with a circuit which passes from terminal X through front contact 55 of track relay TR^B, wires 56 and 71, contact 8—8^a of the circuit controller of signal mechanism S₁^B, wire 72, contact 7—7^b of the circuit controller of signal mechanism S₁^B, wire 73, front contact 74 of distant relay DR^B, wire 75, reverse polar contact 76 of distant relay DR^B, wire 77, front contact 78 of lightout relay LOR^B, wire 79, winding 6 of signal mechanism S₂^B, front contact 80 of distant relay DR^B, wire 81, reverse polar contact 82 of distant relay DR^B, wires 68, 64 and 65, and front contact 66 of track relay TR^B to terminal O. This circuit is closed only when track relay TR^B and lightout relay LOR^B are both energized. Distant relay DR^B is energized in the reverse direction, and signal mechanism S₁^B is swung to its left-hand extreme position; and the current supplied to winding 6 of signal mechanism S₂^B over this circuit is of such polarity that when this circuit is closed the signal mechanism will be swung to the position in which the green roundel is in front of the associated lamp.

Each signal repeater relay is controlled by the associated signal mechanisms S₁ and S₂, by the associated lightout relay LOR, by the associated distant relay DR and by the associated track relay TR. Referring particularly to signal repeater relay SR^E, one circuit for this relay is closed when signal mechanism S₁^B occupies its caution position, signal mechanism S₂^B occupies its proceed position, lightout relay LOR^B is energized, distant relay DR^B is energized in its reverse direction, and track relay TR^B is energized. This circuit passes from terminal X through front contact 55 of track relay TR^B, wires 56 and 71, contact 8—8^a of the circuit controller of signal mechanism S₁^B, wire 72, contact 7—7^b of the circuit controller of signal mechanism S₁^B, wire 73, front contact 74 of distant relay DR^B, wire 75, 76

reverse polar contact 76 of distant relay DR^B, wire 77, front contact 17 of lightout relay LOR^B, wire 78, contact 7-7^a of the circuit controller of signal mechanism S₂^B, wire 83, and the winding of relay SR^B to terminal O. Another circuit for relay SR^B is closed when track relay TR^B is energized, signal mechanism S₁^B occupies its proceed position and signal mechanism S₂^B occupies its stop position, this latter circuit passing from terminal X through front contact 55 of track relay TR^B, wires 56 and 71, contact 7-7^a of the circuit controller of signal S₁^B, wire 72, contact 8-8^b of the circuit controller of signal mechanism S₁^B, wire 84, contact 8-8^b of signal mechanism S₂^B, wire 85, contact 7-7^b of signal mechanism S₂^B, wire 83, and the winding of signal repeater relay SR^B to terminal O.

Each power-off relay POR is controlled in the same manner as in Fig. 2, and the control of this relay need not, therefore, be repeated.

Each distant relay DR is controlled by the associated track relay TR, by the signal repeater relay SR associated with signal S next in advance, by the circuit controller of the signal mechanism S₁ of the signal next in advance, and by the track relay TR for the second block in advance of the associated signal. Referring particularly to relay DR^A, for example, one circuit for this relay passes from terminal X through contact 55 of track relay TR^B, wires 56 and 71, contact 8-8^a of signal mechanism S₁ of signal S^B, wire 86, the winding of relay ALR^B, wire 87, front contact 88-88^a of signal repeater relay SR^B, wire 89, front contact 90 of track relay TR^A, wire 91, the winding of relay DR^A, wire 92, front contact 93-93^a of signal repeater relay SR^B, wire 94, and front contact 95 of track relay TR^B to terminal O. Another circuit for relay DR^A is similar to the circuit just traced with the exception that this latter circuit includes back contacts 86-88^b and 93-93^b of signal repeater relay SR^B instead of front contacts 88-88^a and 93-93^a of signal repeater relay SR^B. A third circuit for distant relay DR^A is similar to the circuit first traced for this relay with the exception that this latter circuit includes contact 7-7^a of signal mechanism S₁^B and wire 72 in place of wire 71 and contact 8-8^a of signal mechanism S₁^B.

It will be noted that each of the circuits for each distant relay includes the approach lighting relay associated with the signal next in advance, and it follows, therefore, that each approach lighting relay will be energized whenever the distant relay next in rear is energized.

Each lamp L₁ is provided with two energizing circuits one of which is closed when the associated approach lighting relay is deenergized and the associated signal repeater relay is energized, and the other of which is closed when the associated signal repeater relay is deenergized, regardless of whether the associated approach lighting relay is energized or deenergized. Each of these energizing circuits includes the low resistance winding 10 of the associated light-out relay connected in multiple with an asymmetric unit P, and each of these circuits is arranged to be supplied with alternating current from the secondary winding 36 of the associated transformer T, or with direct current from the associated battery B according as the power-off relay POR is energized or deenergized. Referring particularly to lamp L₁^B, the one energizing circuit for this lamp normally passes from the left-hand terminal of transformer T^B through front

contact 38-38^a of power-off relay POR^B, wires 95, 96 and 97, back contact 98 of approach lighting relay ALR^B, wire 99, front contact 100-100^a of signal repeater relay SR^B, wire 101, the low resistance winding 10 of lightout relay LOR^B connected in multiple with asymmetric unit P^B, wire 102, the filament of lamp L₁^B, wires 103 and 104, and front contact 47-47^a of power-off relay POR^B to the other terminal of transformer T^B. The other energizing circuit for lamp L₁^B normally passes from the left-hand terminal of transformer T^B through front contact 38-38^a of relay POR^B, wires 95 and 96, back contact 100-100^b of signal repeater relay SR^B, wire 101, the low resistance winding 10 of lightout relay LOR^B connected in multiple with asymmetric unit P^B, wire 102, the filament of lamp L₁^B, wires 103 and 104, and front contact 47-47^a of power-off relay POR^B to the other terminal of secondary winding 36 of transformer T^B. When, however, power-off relay POR^B is deenergized, each of the energizing circuits just traced instead of being supplied with alternating current from the secondary winding 36 of the transformer over front contacts 47-47^a and 38-38^a of power-off relay POR^B, are supplied with direct current from battery E^B over back contacts 38-38^b and 47-47^b of power-off relay POR^B.

Each lamp L₁ is also provided with a checking circuit which is closed when the associated approach lighting and signal repeating relays are both energized provided the filament of the lamp is then intact. Referring particularly to lamp L₁^B, the checking circuit for this lamp may be traced from terminal X through the high resistance winding 9 of lightout relay LOR^B, wire 105, front contact 98-98^a of approach lighting relay ALR^B, wire 99, front contact 100-100^a of signal repeater relay SR^B, wire 101, the low resistance winding 10 of lightout relay LOR^B connected in multiple with rectifier P^B, wire 102, the filament of lamp L₁^B, and wire 103 to terminal O. It will be noted that the low resistance winding 10 and the high resistance winding 9 of the lightout relay LOR^B are connected in series in this checking circuit. The windings 9 and 10 are so arranged that the fluxes set up in the core of relay LOR^B when this circuit is closed will be cumulative, and the parts are so proportioned that when this circuit is closed relay LOR^B will maintain its front contact 17 closed.

Each lamp L₂ is likewise provided with two energizing circuits, each of which is arranged to be supplied with alternating current from the secondary winding 36 of the associated transformer T, or with direct current from the associated battery B according as the associated power-off relay is energized or deenergized. Referring particularly to lamp L₂^B, the one circuit for this lamp is closed only when approach lighting relay ALR^B is deenergized, and normally passes from the left-hand terminal of transformer T^B through front contact 38-38^a of power-off relay POR^B, wires 95, 96, and 97, back contact 103 of approach lighting relay ALR^B, reactor F^B, the filament of lamp L₂^B, wire 106, and front contact 47-47^a of power-off relay POR^B to the right-hand terminal of transformer T^B. The other energizing circuit for the lamp L₂^B is closed when and only when the signal repeater relay SR^B is deenergized, and normally passes from the left-hand terminal of the secondary winding 36 of transformer T^B through front contact 38-38^a of power-off relay POR^B, wire 95, back contact 109 of signal repeater relay 75

SR^B, wire 110, reactor F^B, the filament of lamp L₂^B, wire 106 and front contact 41-41^a of power-off relay POR^B to the other terminal of the secondary winding 36 of transformer T^B. When the power-off relay POR^B is deenergized, each of the circuits just traced for lamp L₂^B are then connected with battery E^B instead of with the secondary winding 36 of transformer T^B in a manner which will be readily understood from an inspection of the drawings, without further description.

It will be noted that each of the circuits for the lamp L₂^B includes the reactor F^B, which, as was previously pointed out, has the same reactance as the low resistance winding 10 of the associated lightout relay LOR^B. It will further be noted that the circuits for the lamp L₂^B are supplied with energy from the same source as the corresponding circuits for the lamp L₁, and since each of the energizing circuits for the lamp L₁ includes the low resistance winding 10 of the associated lightout relay, it follows that both lamps will be supplied with current of the same magnitude.

As shown in the drawings, blocks A-B, B-C and C-D are all unoccupied, but the block to the left of point D is occupied by a train W. Track relays TR^A, TR^B and TR^C are therefore all energized, but track relay TR^D is deenergized.

With track relay TR^D deenergized, all circuits for the winding 6 of signal mechanism S₁^D are interrupted at the front contacts 55 and 66 of this track relay, and the sole circuit for the winding 6 of signal mechanism S₂^D is likewise interrupted at the front contacts 56 and 66 of this track relay, with the result that the red roundel of both signal mechanisms S₁^D and S₂^D is disposed in front of the associated lamps L₁^D and L₂^D. Furthermore, with track relay TR^D deenergized, all circuits for relays ALR^D, SR^D, DR^D and DR^C are open so that these relays are all deenergized. The power-off relays POR are all energized, and since the power-off relay POR^D is energized and signal repeater relay SR^D is deenergized, the energizing circuit for lamp L₁^D including the back contact 100-100^b of signal repeater relay SR^D and secondary winding 36 of transformer T^D is closed, and both circuits for lamp L₂^D including the secondary winding 36 of transformer T^D are closed, so that lamps L₁^D and L₂^D are both lighted. Signal SD therefore indicates stop.

Lightout relay LOR^D is energized by virtue of the energizing circuit which is closed for lamp L₁^D so that its front contact 17 is closed. Track relay TR^C being energized and distant relay DR^C being deenergized, winding 6 of signal mechanism S₁^C is supplied with current of reverse polarity, and winding 6 of signal mechanism S₂^C is deenergized. The yellow roundel of signal mechanism S₁^C is therefore disposed in front of the associated lamp L₁^C, and the red roundel of signal mechanism S₂^C is disposed in front of the lamp L₂^C. With the signal mechanisms S₁^C and S₂^C in the positions just described, all circuits for signal repeater relay SR^C are open, and this relay is therefore deenergized. Since relay SR^C is deenergized, the energizing circuit for lamp L₁^C, including back contact 100-100^b of this relay, is closed and the energizing circuit for lamp L₂^C including back contact 109 of relay SR^C is closed. The lamps L₁^C and L₂^C are therefore both lighted, and signal SC therefore displays a caution indication. Since track relay TR^C is energized and signal mechanism S₁^C occupies its caution position and signal repeater relay SR^C

is deenergized and track relay TR^B is energized, distant relay DR^B is supplied with current of reverse polarity, and approach lighting relay ALR^C is energized. Furthermore, since the one energizing circuit for lamp L₁^C is closed lightout relay LOR^C is also energized.

With distant relay DR^B energized in the reverse direction and track relay TR^B energized, winding 6 of signal S₁^B is supplied with current of reverse polarity, and winding 6 of signal mechanism S₂^B is supplied with current of normal polarity. Signal mechanism S₁^B therefore occupies its extreme left-hand position in which the yellow roundel Y of this mechanism is disposed in front of the lamp L₁^B, and signal mechanism S₂^B occupies its extreme right-hand position in which the green roundel G of this mechanism is disposed in front of the lamp L₂^B. Signal mechanisms S₁^B and S₂^B being in the positions just described, signal repeater relay SR^B is energized and since track relay TR^A is also energized distant relay DR^A is energized in the normal direction and approach lighting relay ALR^B is also energized. Approach lighting relay ALR^B and signal repeater relay SR^B both being energized, the checking circuit for lamp L₁^B is closed, and lamp L₁^B is therefore deenergized, but lightout relay LOR^B is energized. Both circuits for lamp L₂^B are open, and this lamp is therefore also deenergized.

Distant relay DR^A being energized in its normal direction, winding 6 of signal mechanism S₁^A is supplied with current of normal polarity so that the green roundel of this signal mechanism is disposed in front of the lamp L₁^A. Furthermore, winding 6 of signal mechanism S₂^A is deenergized, so that the red roundel of this mechanism is in front of lamp L₂^A. Approach lighting relay ALR^A is energized and signal repeater relay SR^A is also energized. All energizing circuits for the lamps L₁^A and L₂^A are therefore open so that these lamps are deenergized and the checking circuit for lamp L₁^A is therefore closed so that lightout relay LOR^A is energized.

With the apparatus in the positions just described when the train W passes out of the section, to the left of point D, track relay TR^D will pick up and will close its front contacts. When front contacts 56 and 66 of track relay TR^D become closed, a circuit for winding 6 of signal mechanism S₁^D including these contacts and back contacts 60-60^b and 61-61^b of distant relay DR^D will become closed, and signal mechanism S₁^D will therefore move to its right-hand extreme position in which the yellow roundel Y is disposed in front of the lamp L₁^D. As soon as the signal mechanism S₁^D reaches this position, contact 8-8^b of this mechanism will become closed, and will complete one of the circuits for the distant relay DR^C, thus causing this relay to become energized in its reverse direction, and approach lighting relay ALR^D to pick up. The picking up of approach lighting relay ALR^D under these conditions will have no immediate effect on the remainder of the apparatus because signal repeater relay SR^D will still remain deenergized, and as long as this relay remains deenergized the lamps L₁^D and L₂^D will remain lighted by virtue of the energizing circuits for these lamps controlled by relay SR^D.

When distant relay DR^C becomes energized in its reverse direction in the manner just described, the reverse energizing circuit for winding 6 of signal mechanism S₁^C including back contacts 60-60^b and 61-61^b of relay DR^C will become interrupted, and another circuit for winding 6

of signal mechanism S_1^C including front contacts 60—60^a and 61—61^a of relay DR^C will become closed. Signal mechanism S_1^C will remain in the position shown, however, because the current supplied to the winding 6 of this mechanism over both of these circuits flows through the winding in the same direction. The energization of distant relay DR^C under the conditions just described also completes the circuit for winding 6 of signal mechanism S_2^C , and when this circuit becomes closed the mechanism S_2^C will move to its extreme right-hand position in which the green roundel is disposed in front of the lamp L_2^C . The movement of the signal S_2^C to the position just described completes one of the circuits for signal repeater relay SR^C , and relay SR^C therefore picks up and reverses the polarity of the current supplied to distant relay DR^B , thus causing this relay to become energized in its normal condition. The picking up of relay SR^C also interrupts the energizing circuits which were previously closed for the lamps L_1^C and L_2^C and completes the checking circuit for lamp L_1^C . The lamps L_1^C and L_2^C therefore both become extinguished, but relay LOR^C will remain energized for reasons which will be readily understood from the foregoing description.

When relay DR^B becomes energized in its normal direction, it interrupts a circuit which was previously closed for winding 6 of signal mechanism S_1^B and completes another circuit for this mechanism, thus causing this mechanism to move from the position in which the yellow roundel Y is in front of the lamp L_1^B to the position in which the green roundel G is disposed in front of the lamp L_1^B . The energization of the relay DR^B in its normal direction also interrupts, at its polar contacts, the circuit which was previously closed for winding 6 of signal mechanism S_2^B , and this latter mechanism therefore moves from the position in which the green roundel is disposed in front of the lamp L_2^B to the position in which the red roundel R is disposed in front of the lamp L_2^B . The movement of the two signal mechanisms S_1^B and S_2^B from the positions in which they are shown in the drawings to the position just described interrupts one circuit for repeater relay SR^B and completes another circuit for this relay, but due to the slow releasing characteristics of relay SR^B , this relay does not open its front contact under these conditions.

I will now assume that the parts are in the positions in which they are shown in the drawings and that the filament of lamp L_1^B becomes interrupted for some reason. Under these conditions, the checking circuit for lamp L_1^B will, of course, become interrupted at the lamp filament, and lightout relay LOR^B will therefore become deenergized and will open its front contact 17. The opening of this contact will cause winding 6 of signal mechanism S_2^B to become deenergized, and when this winding becomes deenergized, signal mechanism S_2^B will move to the position in which the red roundel R is disposed in front of the associated lamp L_2^B , thereby interrupting the circuit for signal repeater relay SR^B and, hence, causing this latter relay to become deenergized. The deenergization of relay SR^B , in turn, will cause lamp L_2^B to become lighted, so that the lower mechanism of this signal will now display what is usually regarded as a stop aspect. The deenergization of relay SR^B will also reverse the polarity of the current supplied to distant relay DR^A , and as a result, the mechanism S_1^A of signal S^A will move from the position shown to the posi-

tion in which the yellow roundel Y is disposed in front of the lamp L_1^A . As soon as the mechanism reaches this latter position, the circuit for the winding 6 of the mechanism S_2^A will become closed and will cause the mechanism S_2^A to move to the position in which the green roundel is in front of the lamp L_2^A . It will be seen, therefore, that if a train now enters the block to the right of signal S^A , this signal will display a caution indication rather than a proceed indication, and the train will therefore be prepared to stop when it reaches signal S^B , thus preventing the undesirable condition of having the train pass a signal which indicates proceed or approach restricting, only to be required to stop at the next signal.

It should be particularly pointed out that in signal systems of the type shown in Fig. 3, as they have heretofore generally been constructed, it has been customary to employ in place of the two winding lightout relays LOR , a single winding lightout relay which was normally deenergized but which became energized when the lamp of the upper signal mechanism S_1 became lighted, and to include in the control circuit for the winding 6 of the lower signal mechanism, in addition to a front contact of the lightout relay corresponding to the contact 17 in the drawings, a front contact of the approach lighting relay which latter contact was connected in multiple with the front contact of the lightout relay, and which served to maintain the circuit for the winding 6 of the lower signal mechanism closed under the proper traffic conditions, even though the signal was then dark. With this arrangement, when a train approached the signal while the circuit for the winding 6 of the lower mechanism was closed, the resultant deenergization of the associated approach lighting relay caused the circuit for the winding 6 to become interrupted during the interval of time which elapsed between the opening of the front contacts of the approach lighting relay and the closing of the front contacts of the lightout relay, and this interruption of the circuit for the winding 6 permitted the lower signal mechanism to start to return to its stop position, with the result that this lower mechanism sometimes gave a momentary red blink. This blink is undesirable, and with my present invention, due to the fact that each lightout relay is energized regardless of whether the signal is dark or lighted as long as the lamp filament of the upper signal mechanism is intact, and to the further fact that the rectifier P which is connected in multiple with the low resistance winding 10 of the lightout relay renders the lightout relay slow releasing, completely eliminates this undesirable blink.

Under some conditions it is desirable to so control the signals of a system such as that shown in Figs. 3 and 3^a, that, if the filament of the lamp for the upper mechanism S_1 of a signal becomes interrupted for any reason at any time except when the associated signal is displaying a stop indication, both mechanisms of such signal will immediately move to the positions which these mechanisms occupy when the signal is displaying a stop indication, and the mechanisms of each of the signals in the rear of such signal will move to the positions that these latter mechanisms would normally occupy when the signal having the burned out lamp is displaying a stop indication. This result may be accomplished by modifying the control circuits at each signal location in the manner shown in connection with location A in Fig. 4. Referring to Fig. 4, as here shown, 75

the lightout relay LOR^A has been provided with an additional front contact 121, and this contact together with the contact 17 has been included in all those circuits which are controlled by the track relay TR^A with the exception of the circuit for relay DR^A . With the circuits modified in this manner, if the filament of lamp L_1^A becomes interrupted for any reason, lightout relay LOR^A will, of course, become deenergized, and as a result, if the winding 6 of each of the signal mechanisms S_1^A and S_2^A is not already deenergized, it will become deenergized, thus causing both of these mechanisms to move to the position in which the red roundel of the mechanism is in front of the associated lamp. Furthermore, if signal repeater relay SR^A and approach lighting relay ALR^A are not already deenergized, these relays will become deenergized due to the movement of the signal mechanisms and will thus cause the lamp L_2^A to become energized and the mechanisms of the two signals next in rear of signal S^A to move to the positions which these last named mechanisms normally occupy when signal S^A is displaying a stop indication.

Referring now to Figs. 5 and 5^a, as here shown, each block is provided, in place of the searchlight type of signals shown in Figs. 3 and 3^a, with a color light signal comprising an upper unit U made up of a green lamp G, a yellow lamp Y, and a red lamp R, and a lower unit L made up of a green lamp G and a red lamp R. When the red lamps of both units of a signal are lighted, the signal indicates stop; when the yellow lamp of the upper unit and the red lamp of the lower unit are both lighted, the signal indicates caution; when the yellow lamp of the upper unit and the green lamp of the lower unit are lighted, the signal indicates approach restricting; and when the green lamp of the upper unit and the red lamp of the yellow unit are both lighted, the signal indicates proceed. The relays and other apparatus shown in Figs. 5 and 5^a are similar to those shown in Figs. 3 and 3^a with the exception that no signal repeater relays are provided as in Figs. 3 and 3^a since these relays are unnecessary with the type of signals shown in Figs. 5 and 5^a.

Each distant relay as shown in Figs. 5 and 5^a is controlled by the associated track relay TR , by the distant relay DR for the signal next in advance and by the track relay associated with the signal next in advance over a polarized line circuit which is supplied with current of normal or reverse polarity according as the distant relay for the signal next in advance is picked up or released, and which includes the winding of the approach lighting relay for the signal next in advance. Referring particularly to distant relay DR^C , when track relays TR^C and TR^D are both energized and distant relay DR^D is also energized, the polarized line circuit for this relay passes from terminal X through the winding of approach lighting relay ALR^D , wire 120, front contact 121 of track relay TR^D , front contact 123-123^a of distant relay DR^D , line wire 124, front contact 125 of track relay TR^C , the winding of distant relay DR^C , front contact 126 of track relay TR^C , line wire 127, and front contact 128-128^a of distant relay DR^D to terminal O. When, however, track relays TR^C and TR^D are both energized and distant relay DR^D is deenergized, this circuit then includes back contacts 123-123^b and 128-128^b of distant relay DR^D in place of front contacts 123-123^a and 128-128^a of distant relay DR^D . It will be seen,

therefore, that when track relays TR^C and TR^D and distant relay DR^D are all energized, distant relay DR^C will be supplied with current of normal polarity and that when track relays TR^C and TR^D are both energized and distant relay DR^D is deenergized, distant relay DR^C will be supplied with current of reverse polarity; but that, when either track relay TR^C or track relay TR^D is deenergized, distant relay DR^C will be deenergized.

It should be noted that since the circuit for each distant relay includes the winding of the approach lighting relay for the signal next in advance, each approach lighting relay will be energized or deenergized according as the distant relay for the signal next in rear is energized or deenergized.

Each power-off relay POR is controlled in the same manner as in the preceding views, and the control of these relays need not, therefore, be repeated.

The signal lamp G of the upper unit U of each signal S is provided with an energizing circuit which is supplied with alternating or direct current according as the associated power-off relay 25 is energized or deenergized, and which is closed when and only when the associated approach lighting relay ALR is deenergized and the associated distant relay is energized in its normal direction. Referring particularly to the lamp G 30 of the upper unit U of the signal S^A , for example, the circuit for this lamp normally passes from the left-hand terminal of the secondary winding 36 of transformer T^A through wire 48, front contact 47-47^a of power-off relay POR^A , 35 wires 128 and 135, the low resistance winding 10 of lightout relay LOR^D connected in multiple with asymmetric unit P^A , wire 136, front contact 137-137^a of track relay TR^A , wire 138, front contact 139-139^a of distant relay DR^A , 40 wire 140, back contact 141-141^b of approach lighting relay ALR^A , normal polar contact 142-142^a of distant relay DR^A , wire 143, the filament of lamp G, wire 144, back contact 145-145^a of approach lighting relay ALR^A , wires 45 146, 147, 148 and 149, front contact 38-38^a of power-off relay POR^A and wire 37 to the other terminal of the secondary winding 36 of transformer T^A . When power-off relay POR^A is deenergized, the circuit for lamp G then includes 50 battery E^A and back contacts 47-47^b and 38-38^b of power-off relay POR^A in place of secondary winding 36 of transformer T^A and front contacts 47-47^a and 38-38^a of power-off relay POR^A .

The lamp G of the upper unit U of each signal S is also provided with a checking circuit which is closed when and only when the associated approach lighting relay ALR is energized and the associated distant relay DR is energized in its normal direction, and which includes the high 55 resistance winding 9 of the associated lightout relay LOR . Referring particularly to the lamp G of the upper unit U of the signal S^A , for example, the checking circuit for the lamp G of this signal passes from terminal X through the high 60 resistance winding 9 of lightout relay LOR^A , front contact 141-141^a of approach lighting relay ALR^A , polar contact 142-142^a of distant relay DR^A , wire 143, the filament of lamp G of the upper unit U of signal S^A , wires 144 and 150, and 70 front contact 145-145^a of approach lighting relay ALR^A to terminal O.

It will be noted that the energizing circuit for the lamp G of the upper unit U of each signal S includes the low resistance winding 10 of the 75

associated lightout relay LOR, while the checking circuit for the lamp G of the upper unit U of each signal S includes the high resistance winding 9 of the associated lightout relay. The parts are so proportioned that when either of these circuits is closed, the associated lightout relay will hold its front contacts closed.

The lamp Y of the upper unit U of each signal S is provided with a first energizing circuit which is supplied with alternating current from the secondary winding 36 of the associated transformer T or with direct current from the associated standby battery E according as the associated power-off relay POR is energized or deenergized, and which is closed when and only when the associated distant relay DR is energized in its reverse direction, the associated track relay TR is energized, and the associated approach lighting relay ALR is deenergized. The signal lamp Y of the upper unit U of each signal S is also provided with a second energizing circuit which is likewise supplied with alternating current from the secondary winding 36 of the associated transformer T or with direct current from the associated standby battery E according as the associated power-off relay POR is energized or deenergized, and which is closed when and only when the associated distant relay DR is deenergized, and the associated track relay TR is energized. Referring particularly to the lamp Y of the upper unit U of signal S^A, when the power-off relay POR^A is energized, the first energizing circuit may be traced from the left-hand terminal of the secondary winding 36 of transformer T^A, through wire 48, front contact 47-47^a of power-off relay POR^A, wires 128 and 135, the low resistance winding 10 of lightout relay LOR^A connected in multiple with asymmetric unit P^A, wire 136, front contact 137-137^a of track relay TR^A, wire 138, front contact 139-139^a of distant relay DR^A, wire 140, back contact 141-141^b of approach lighting relay ALR^A, reverse polar contact 142-142^b of distant relay DR^A, wires 151 and 152, the filament of lamp Y, wire 153, front contact 154-154^b of distant relay DR^A, wire 150, back contact 145-145^a of approach lighting relay ALR^A, wires 146, 147, 148 and 149, front contact 38-38^a of power-off relay POR^A, and wire 37 to the right-hand terminal of secondary winding 36 of transformer T^A. When power-off relay POR^A is deenergized, the circuit for lamp G then includes the standby battery E^A and back contacts 47-47^b and 38-38^b of power-off relay POR^A in place of the secondary winding 36 of transformer T^A, and front contacts 47-47^a and 38-38^a of power-off relay POR^A. The second energizing circuit for lamp Y of the upper unit U of signal S^A, when power-off relay POR^A is energized, may be traced from the left-hand terminal of secondary winding 36 of transformer T^A through wire 48, front contact 47-47^a of power-off relay POR^A, wires 128 and 135, the low resistance winding 10 of the lightout relay LOR^A connected in multiple with asymmetric unit P^A, wire 136, front contact 137-137^a of track relay TR^A, wire 138, back contact 139-139^b of distant relay DR^A, wire 152, the filament of lamp Y, wire 153, back contact 154-154^b of distant relay DR^A, wires 147, 148 and 149, front contact 38-38^a of power-off relay POR^A, and wire 37 to the other terminal of the secondary winding 36 of transformer T^A. When, however, power-off relay POR^A is deenergized, this circuit then includes the battery E^A and back contacts 38-38^b and 47-47^b of power-off relay POR^A in place of front contacts

38-38^a and 47-47^a of power-off relay POR^A and secondary winding 36 of transformer T^A.

The lamp Y of the upper unit U of each signal S is also provided with a checking circuit which is closed when and only when the associated approach lighting relay ALR is energized and the associated distant relay DR is energized in its reverse direction, and which includes the high resistance winding 9 of the associated lightout relay LOR. Referring particularly to the lamp Y of the upper unit U of signal S^A, the checking circuit for this lamp passes from terminal X through winding 9 of lightout relay LOR^A, front contact 141-141^a of approach lighting relay ALR^A, reverse polar contact 142-142^a of distant relay DR^A, wires 151 and 152, the filament of lamp Y, wire 153, front contact 154-154^a of distant relay DR^A, wire 150, and front contact 145-145^a of approach lighting relay ALR^A to terminal O.

It will be noted that the two energizing circuits for the lamp Y of each unit U of each signal include the low resistance winding 10 of the associated lightout relay LOR, while the checking circuit for such lamp includes the high resistance winding 9 of the associated lightout relay LOR. It will be apparent, therefore, that when either of the energizing circuits or the checking circuit for a lamp Y is closed, the associated lightout relay LOR will be energized.

The lamp R of the upper unit U of each signal S is provided with an energizing circuit which is supplied with alternating current from the secondary winding 36 of the associated transformer T, or with direct current from the associated standby battery E, according as the associated power-off relay POR is energized or deenergized, and which is closed whenever the associated track relay TR and the associated approach lighting relay ALR are both deenergized. Referring particularly to signal S^A, the energizing circuit for the lamp R of the upper unit U of this signal may be traced from the left-hand terminal of the secondary winding 36 of transformer T^A through wire 48, front contact 47-47^a of power-off relay POR^A, wires 128 and 135, the low resistance winding 10 of lightout relay LOR^A connected in multiple with asymmetric unit P^A, wire 136, back contact 137-137^b of track relay TR^A, wire 156, the filament of lamp R, wires 157, 148 and 149, front contact 38-38^a of power-off relay POR^A, and wire 37 to the other terminal of the secondary winding 36 of transformer T^A. When the power-off relay POR^A is deenergized, this circuit then includes battery E^A and the back contacts of power-off relay POR^A instead of the secondary winding 36 of transformer T^A and the front contacts of power-off relay POR^A. It will be apparent that this circuit also includes the low resistance winding 10 of the associated lightout relay so that when this circuit is closed the associated lightout relay will also be energized.

The green lamp G of the lower unit L of each signal S is provided with an energizing circuit which is supplied with alternating current from the secondary winding 36 of the associated transformer T, or with direct current from the associated standby battery E according as the associated power-off relay POR is energized or deenergized, and which is closed when and only when the associated distant relay DR is energized in its reverse direction, the associated lightout relay LOR is energized, and the associated approach lighting relay ALR is deenergized. Referring particularly to signal S^A, the circuit for the lamp

G of the lower unit L of this signal when power-off relay POR^A is energized may be traced from the left-hand terminal of the secondary winding 36 of transformer T^A through wire 48, front contact 47-47^a of power-off relay POR^A, wire 128, a reactor F^A having the same impedance as the low resistance winding 19 of the associated light-out relay LOR^A, front contact 130-130^a of distant relay DR^A, wire 131, back contact 132 of approach lighting relay ALR^A, reverse polar contact 133-133^a of distant relay DR^A, wire 158, front contact 159-159^a of lightout relay LOR^A, wire 160, the filament of lamp G, wire 149, front contact 38-38^a of power-off relay POR^A, and wire 37 to the other terminal of the secondary winding 36 of transformer T^A. When power-off relay POR^A is deenergized, battery E^A is included in the circuit just traced in place of the secondary winding 36 of transformer T^A in a manner which will be readily understood from an inspection of the drawings and from the foregoing description without further detailed description.

The red lamp R of the lower unit L of each signal S is provided with two energizing circuits. Referring particularly to signal S^A, the one energizing circuit for the lamp R of the lower unit L of this signal is closed when and only when the associated distant relay DR is deenergized, and normally passes from the left-hand terminal of the secondary winding 36 of transformer T^A through wire 48, front contact 47-47^a of power-off relay POR^A, wire 128, reactor F^A, back contact 130-130^a of distant relay DR^A, wire 155, the filament of lamp R, wire 149, front contact 38-38^a of power-off relay POR^A, and wire 37 to the right-hand terminal of the secondary winding 36 of transformer T^A. The other energizing circuit for the lamp R of the lower unit L of signal S^A is closed when distant relay DR^A is energized in its normal direction and approach lighting relay ALR^A is deenergized, and normally passes from the right-hand terminal of the secondary winding 36 of transformer T^A through wire 48, front contact 47-47^a of power-off relay POR^A, wire 128, reactor F^A, front contact 130-130^a of distant relay DR^A, wire 131, back contact 132 of approach lighting relay ALR^A, normal contact 133-133^a of distant relay DR^A, wires 134 and 155, the filament of lamp R, wire 149, front contact 38-38^a of power-off relay POR^A, and wire 37 to the right-hand terminal of the secondary winding 36 of transformer T^A. When power-off relay POR^A is deenergized, each of the circuits just traced for the lamp R of the lower unit L of signal S^A is then supplied with current from battery E^A instead of from secondary winding 36 of transformer T^A in a manner which will be obvious from an inspection of the drawings. The energizing circuits for the lamps R of the lower units L of each of the remaining signals are similar to those just traced for the lamp R of the lower unit L of the signal S^A.

As shown in the drawings, sections A-B, B-C and C-D are all unoccupied but the section to the left of point D is occupied by a train W. Track relays TR^A, TR^B, and TR^C are therefore all energized, but track relay TR^D is deenergized. The power-off relays POR are all energized. Since track relay TR^D is deenergized, the circuit for distant relay DR^D is open at front contacts 125 and 126 of track relay TR^D, and the circuit for distant relay DR^C is open at front contact 121 of track relay TR^D. Distant relays DR^D and DR^C are, therefore, both deenergized, and ap-

proach lighting relay ALR^D is also deenergized. The circuit for the lamp R of the upper unit U of signal S^D including back contact 131-131^b of track relay TR^D is therefore closed, so that this lamp is lighted, and the circuit for the lamp R of the lower unit L of signal S^D including back contact 130-130^b of distant relay DR^D is also closed, so that this lamp is also lighted. Signal S^D is, therefore, displaying a stop indication. Furthermore, since lamp R of upper unit U of signal S^D is lighted, lightout relay LOR^D is picked up.

Track relay TR^C being energized and distant relay DR^C being deenergized, the circuit for lamp Y of signal S^C including front contact 137-137^a of track relay TR^C and back contacts 154-154^b and 130-130^b of distant relay DR^C is closed, so that lamp Y of this signal is lighted. Furthermore, since distant relay DR^C is deenergized the circuit for lamp R of the lower unit L of signal S^C including back contact 138-138^b of distant relay DR^C is closed, and this lamp is therefore also lighted. Signal S^C accordingly indicates caution. Lightout relay LOR^C is energized by virtue of the circuit for lamp Y of signal S^C. Distant relay DR^B is supplied with current of reverse polarity and approach lighting relay ALR^C is also energized.

Distant relay DR^B being energized in its reverse direction, and track relays TR^A and TR^B both being energized, distant relay DR^A is energized in its normal direction, and approach lighting relay ALR^B is therefore also energized. Since relays DR^B and ALR^B are both energized, all circuits for the lamps of signal S^B are open, and these lamps are therefore all dark. The checking circuit for lamp Y of the upper unit U of signal S^B is closed, however, and lightout relay LOR^B is therefore also energized. All relays at location A are energized, and all lamps of signals S^A are accordingly extinguished.

I will now assume that the parts are in the positions just described, and that a train moving toward the left enters section A-B. When the train enters section A-B, approach lighting relay ALR^A will be deenergized due to the previous deenergization of the track relay for the section to the right of point A, and the upper green lamp and the lower red lamp of signal S^A will therefore be lighted. The entrance of the train into section A-B will deenergize track relay TR^A, and the deenergization of this track relay, in turn, will interrupt the circuit over which distant relay DR^A was previously energized, so that this relay will become deenergized. The deenergization of distant relay DR^A will interrupt the circuits which were previously closed for the upper green lamp and the lower red lamp of signal S^A, and will complete the energizing circuit for the upper red lamp R of signal S^A and another energizing circuit for the lower red lamp of signal S^A. The upper green lamp of signal S^A will therefore become extinguished and the upper red lamp will become lighted, while the lower red lamp will remain lighted, thus causing signal S^A to display a stop indication. It should be noted that during the interval which elapses between the interrupting of the circuit for the upper green lamp G of signal S^A and the closing of the circuit for the upper red lamp of this signal, lightout relay LOR^A will become momentarily deenergized. This relay, however, is rendered sufficiently slow releasing by the asymmetric unit P^A to prevent its front contact opening and its back contact closing under these conditions.

When distant relay DR^A becomes deenergized due to the entrance of the train into block A—B, approach lighting relay ALR^B will also become deenergized, and as a result the lamp Y of the upper unit U of signal S^B and the green lamp G of the lower unit L of signal S^B will both become lighted, thus causing signal S^B to display an approach restricting indication. When the train enters block B—C, track relay TR^B will become deenergized and will thus deenergize distant relay DR^B . The deenergization of this relay will cause the yellow lamp of the upper unit U of signal S^B and the green lamp of lower unit L of signal S^B to become extinguished and both red lamps of this signal to become lighted. The indication of signal S^B will, therefore, change from approach restricting to stop. The deenergization of relay DR^B will also cause approach lighting relay ALR^C to become deenergized, but the indication displayed by signal S^C will not change since the upper lamp Y and the lower lamp R of this signal are already illuminated. When the train passes completely out of section A—B, approach lighting relay ALR^A will pick up, and the picking up of this relay will cause the indication displayed by signal S^A to change from stop to caution. When the train enters section C—D, track relay TR^C will become deenergized, but no further change in the apparatus will take place. Since signal S^D is then displaying a stop indication, the train will be required to stop until the preceding train W has passed out of the block to the left of point D. When the train has passed completely out of section B—C, the resultant picking up of track relay TR^B will cause current of reverse polarity to be supplied to distant relay DR^A and this relay will, therefore, become energized in its reverse direction. The energization of relay DR^A will interrupt the circuits which were previously closed for the upper lamp Y and the lower lamp R of signal S^A , and these lamps will, therefore, become extinguished.

If when the parts are in the positions shown in the drawings, the filament of either the upper red lamp R of signal S^D or the yellow lamp Y of signal S^C becomes burned out, the associated light out relay LOR will become deenergized. The deenergization of these lightout relays, however, will have no immediate effect on the remainder of the apparatus. If, however, a train approaches the signal having the burned out lamp, only the lower red lamp R of such signal will become lighted, and the train will, by the rules of the railroad, be required to stop.

I will now assume that with the parts in the positions in which they are shown in the drawings, the filament of the lamp Y of signal S^B becomes broken, and that a train subsequently enters block A—B. When the filament of lamp Y becomes broken, it will interrupt the checking circuit which was previously closed for this lamp, and lightout relay LOR^B will therefore become deenergized, and will open its front contact $159-159^a$ and close its back contact $159-159^b$. When the train enters section A—B, the resultant deenergization of track relay TR^A will cause approach lighting relay ALR^B to become deenergized in the manner previously described, and when this relay becomes deenergized the circuit which would normally become closed for the lower green lamp G of signal S^B including front contact $159-159^a$ of lightout relay LOR^A will then be open at front contact $159-159^a$, and an auxiliary circuit for the red lamp R including back contact $159-159^b$ of

lightout relay LOR^B will become closed. This latter circuit may be traced from the right-hand terminal of the secondary winding 36 of transformer T^B through wire 48, front contact $47-47^a$ of power-off relay POR^A , wire 128, reactor F^B , front contact $130-130^a$ of distant relay DR^B , wire 131, back contact 132 of approach lighting relay ALR^B , reverse polar contact $133-133^b$ of distant relay DR^B , back contact $159-159^b$ of light-out relay LOR^B , wires 134 and 155, the filament of lamp R, wire 149, front contact $38-38^a$ of power-off relay POR^B , and wire 37 to the other terminal of the secondary winding 36 of transformer T^B . The red lamp R will, therefore, become lighted, thus requiring the engineer to stop the train.

It should be particularly pointed out that in signaling systems of the type shown in Figs. 5 and 5^a as they have heretofore generally been constructed, it has been customary to employ in place of the two winding lightout relays LOR a single winding lightout relay which was only energized when the signal was displaying an indication. As a result, when traffic conditions in advance were such that if a train entered a block under such conditions that the signal which is being approached by the train would display its approach restricting indication, the lightout relay would not become energized until after the yellow lamp Y became energized so that a circuit would be normally completed for the lower red lamp R over the back contact of this lightout relay, which circuit would immediately become interrupted and the circuit for the lower lamp G would become closed. The signal would, therefore, momentarily display a yellow over red indication which would immediately change to a green indication, which condition was undesirable. With apparatus embodying my present invention, however, inasmuch as the lightout relays are normally energized whether the signal is lighted or dark, so long as the filaments of the upper groups of lamps are intact, and since the lightout relays are rendered slow acting due to the associated rectifiers, this blink will be prevented.

Referring now to Figs. 6 and 6^a, the relays, track circuits and signals in the form of my invention here shown are identical with those shown in Figs. 5 and 5^a, but the control circuits for the signals and for certain ones of the relays have been changed in such manner that if the filament of either the green or yellow lamp of the upper unit U of a signal becomes broken or burned out at any time when the signal is not displaying a stop indication, such signal will immediately be caused to display a stop indication, and the apparatus associated with the two signals next in rear will be so conditioned that if a train approaches either one of such signals, it will display the same indication which it would have displayed if the signal having the burned out lamp had been caused to display its stop indication due to traffic conditions in advance.

The control circuits for the distant relays DR as shown in Fig. 6 are identical with those shown in Figs. 5 and 5^a except for the fact that a front contact 165 of the lightout relay associated with the signal next in advance has been included in each of these circuits. It will be seen, therefore, that with the apparatus constructed as shown in Figs. 6 and 6^a, if any one of the lightout relays becomes deenergized it will deenergize the associated approach lighting relay and the distant relay for the signal next in rear.

The power-off relays as shown in Figs. 6 and 6^a

are controlled in exactly the same manner as in Figs. 5 and 5a.

The signal lamp G of the upper unit U of each signal, as shown in Figs. 6 and 6a, is provided with a circuit which is controlled by the associated track relay, the associated distant relay and the associated approach lighting relay in such manner that this circuit will become closed when and only when the three blocks next in advance are all unoccupied and the block next in rear is occupied. Referring particularly to lamp G of the upper unit U of signal S^A, for example, when power-off relay POR^A is energized, the circuit for this lamp passes from the left-hand terminal of the secondary winding 36 of transformer T^A through wire 48, front contact 47-47^a of power-off relay POR^A, wire 166, front contact 137-137^a of track relay TR^A, wire 167, front contact 139-139^a of distant relay DR^A, back contact 141-141^b of approach lighting relay ALR^A, normal contact 142-142^a of distant relay DR^A, wire 168, the filament of lamp G, wire 169, the winding 10 of lightout relay LOR^A connected in multiple with asymmetric unit P^A, wire 170, front contact 154-154^a of distant relay DR^A, wire 171, back contact 145-145^b of approach lighting relay ALR^A, wires 172 and 173, front contact 38-38^a of power-off relay POR^A, and wire 37 to the right-hand terminal of the secondary winding 36 of transformer T^A.

When power-off relay POR^A is deenergized, the energizing circuit for lamp G of signal S^A, instead of being supplied with alternating current from the secondary winding 36 of transformer T^A, is then supplied with direct current from battery E^A in a manner which will be readily understood from an inspection of the drawings without further description.

It will be noted that the energizing circuit just traced for lamp G includes the winding 10 of the associated lightout relay LOR^A and it follows, therefore, that whenever this circuit is closed, the lightout relay LOR^A will be energized.

The lamp G of the upper unit U of each signal S is also provided with a checking circuit which is controlled by the associated distant and approach lighting relays, and which is closed when and only when these relays are both energized. Referring particularly to the lamp G of the upper unit U of signal S^A, the checking circuit for this lamp may be traced from terminal X through winding 9 of relay LOR^A, front contact 141-141^a of approach lighting relay ALR^A, normal polar contact 142-142^a of distant relay DR^A, wire 168, the filament of lamp G, wire 169, winding 10 of lightout relay LOR^A connected in multiple with asymmetric unit P^A, wire 170, front contact 154-154^a of distant relay DR^A, wire 171, and front contact 145-145^b of approach lighting relay ALR^A to terminal O. It should be pointed out that when this checking circuit is closed, lightout relay LOR^A will be energized.

When traffic conditions are such that the green lamp G of the upper unit U of the signal S is lighted, the red lamp R of the lower unit L of such signal is then normally also lighted to cause this signal to display a proceed indication by virtue of a first circuit which is controlled by the associated distant and approach lighting relays. Referring particularly to the red lamp R of the lower unit L of the signal S^A, the first circuit for this lamp when power-off relay POR^A is energized passes from the left-hand terminal of the secondary winding 36 of transformer T^A through wire 48, front contact 47-47^a of power-off relay

POR^A, wire 174, reactor F^A, front contact 130-130^a of distant relay DR^A, wire 175, back contact 132 of approach lighting relay ALR^A, normal polar contact 133-133^a of distant relay DR^A, wire 134, the filament of lamp R, wire 175, front contact 38-38^a of power-off relay POR^A, and wire 37 to the other terminal of secondary winding 36 of transformer T^A. When power-off relay POR^A is deenergized, this circuit is then supplied with direct current from battery E^A in an obvious manner.

The lamp Y of the upper unit U of each signal S is provided with a first energizing circuit which is controlled by the associated track relay, by the associated distant relay, and by the associated approach lighting relay, and which is closed when and only when the two blocks next in advance are both unoccupied, and the block next in rear is occupied. Referring particularly to the lamp Y of the upper unit U of signal S^B, the first energizing circuit for this lamp may be traced from the left-hand terminal of the secondary winding 36 of transformer T^B, through wire 48, front contact 47-47^a of power-off relay POR^B, wire 166, front contact 137-137^a of track relay TR^B, wire 167, front contact 139-139^a of distant relay DR^B, back contact 141-141^b of approach lighting relay ALR^B, reverse polar contact 142-142^b of distant relay DR^B, wires 176 and 177, the filament of lamp Y, wire 169, the winding 10 of lightout relay LOR^B connected in multiple with asymmetric unit P^B, wire 170, front contact 154-154^a of distant relay DR^B, wire 171, back contact 145-145^b of approach lighting relay ALR^B, wires 172 and 173, front contact 38-38^a of power-off relay POR^B, and wire 37 to the other terminal of power-off relay POR^B. It should be noted that when power-off relay POR^B is deenergized this circuit will then be supplied with direct current from the battery E^B. It should also be noted that since this circuit includes the winding 10 of the lightout relay LOR^B, this lightout relay will be energized whenever this circuit is closed.

When the first circuit for the lamp Y of the upper unit U of a signal S is closed, a circuit is normally also closed for the green lamp G of the lower unit L of the associated signal to cause the signal to display an approach restricting indication. Referring particularly to the green lamp G of the lower unit L of signal S^B, the circuit for this lamp may be traced from the left-hand terminal of the secondary winding 36 of transformer T^B through wire 48, front contact 47-47^a of power-off relay POR^B, wire 174, reactor F^B, front contact 130-130^a of distant relay DR^B, wire 175, back contact 132 of approach lighting relay ALR^B, reverse polar contact 133-133^b of distant relay DR^B, wire 158, front contact 159-159^a of lightout relay LOR^B, wire 178, the filament of lamp G, wire 175, front contact 38-38^a of power-off relay POR^B, and wire 37 to the other terminal of the secondary winding 36 of transformer T^B.

The yellow lamp Y of the upper unit U of each signal S is also provided with another energizing circuit which is controlled by the associated distant and track relays, and which is closed when and only when the second block in advance is occupied and the first block in advance is unoccupied. Referring particularly to the lamp Y of the upper unit U of signal S^B, the second energizing circuit for this lamp normally passes from the right-hand terminal of secondary winding 36 of transformer T^B, through wire 48, front con-

tact 47-47^a of power-off relay POR^B, wire 166, front contact 137-137^a of track relay TR^B, wire 167, back contact 139-139^b of distant relay DR^B, wire 177, the filament of lamp Y, wire 169, winding 10 of light-out relay LOR^A connected in multiple with asymmetric unit PB, wire 170, back contact 154-154^b of distant relay DR^B, wire 173, front contact 38-38^a of power-off relay POR^B, and wire 37 to the other terminal of the secondary winding 36 of transformer T^B. It should be noted that this latter circuit for the lamp Y of signal S^B also includes the winding 10 of lightout relay LOR^B, so that lightout relay LOR^B will be energized whenever this circuit is closed.

15 When this second circuit for the lamp Y of signal S is closed, a second circuit for the red lamp R of the associated signal is normally also closed to cause the signal to display a caution indication, which latter circuit is also controlled by the associated distant relay. Referring particularly to the red lamp R of the lower unit L of the signal S^B, the second circuit for this lamp normally passes from the left-hand terminal of the secondary winding 36 of transformer T^B, 25 through wire 48, front contact 47-47^a of power-off relay POR^B, wire 174, reactor FB, back contact 130-130^b of distant relay DR^B, wire 179, the filament of lamp R of the lower unit L of signal S^B, wire 175, front contact 38-38^a of power-off relay POR^B, and wire 37 to the other terminal of the secondary winding 36 of transformer T^B.

30

The lamp Y of the upper unit U of each signal S is further provided with a checking circuit which is closed when and only when the two blocks next in advance and the block next in rear of the signal are all unoccupied. Referring particularly to the lamp Y of signal S^B, the checking circuit for this lamp passes from terminal X through winding 9 of lightout relay LOR^B, front contact 141-141^a of approach lighting relay ALR^B, reverse polar contact 142-142^b of distant relay DR^B, wires 176 and 177, the filament of lamp Y of signal S^B, wire 169, winding 10 of lightout relay LOR^B connected in multiple with asymmetric unit PB, wire 170, front contact 154-154^a of distant relay DR^B, wire 171, and front contact 145-145^a of approach lighting relay ALR^B to terminal O. It will be noted that this latter circuit includes the two windings 9 and 10 of lightout relay LOR^B connected in series, and it should be pointed out that whenever this circuit is closed this relay will be energized.

The red lamp R of the upper unit U of each signal S is provided with an energizing circuit which is controlled by the associated track relay, and which is closed whenever this relay is deenergized, as is the case when a train occupies the block immediately in advance of the signal. Referring particularly to signal S^B, the circuit for the red lamp R of the upper unit U of this signal normally passes from the left-hand terminal of the secondary winding 36 of transformer T^B through wire 48, front contact 47-47^a of power-off relay POR^B, wire 166, back contact 137-137^b of track relay TR^B, wire 180, the filament of the lamp R of the upper unit U of signal S^B, wire 175, front contact 38-38^a of power-off relay POR^B and wire 37 to the other terminal of the secondary winding 36 of transformer T^B.

When the circuit for the lamp R of the upper unit U of a signal S is closed, the lower red lamp R is then normally energized over the second circuit for this lamp, thus causing this signal to display a stop indication.

As shown in the drawings, sections A-B, B-C, and C-D are all unoccupied but the section to the left of point D is occupied by a train W. Track relays TR^A, TR^B and TR^C are, therefore, all energized while track relay TR^D is deenergized. The power-off relays POR are all energized. Since track relay TR^D is deenergized, the circuit for distant relay DR^D and the circuit for distant relay DR^C are both open at the front contacts of track relay TR^D, and these relays and approach lightout relay ALR^D are, therefore, all deenergized. Furthermore, with track relay TR^D deenergized, the circuit for the red lamp R of the upper unit U of signal S^D, including back contact 137-137^b of track relay TR^D is closed, and with approach lighting relay ALR^D deenergized the circuit for the red lamp R of the lower unit L of signal S^D is also closed, and signal S^D is, therefore, displaying a stop indication. The energizing circuits for the lamps G and Y of the upper unit U of signal S^D are both open at front contact 137-137^a of track relay TR^D and the checking circuits for both of these lamps are open at front contacts 154-154^a of distant relay DR^D so that lightout relay LOR^D is also deenergized. The circuit for the green lamp G of the lower unit L of signal S^D is interrupted at front contact 130-130^b of distant relay DR^A and also at polar contact 133-133^b of distant relay DR^B and this lamp is, therefore, also extinguished.

Track relay TR^C being energized and distant relay DR^C being deenergized, the second circuit for the lamp Y of the upper unit U and the second circuit for the lamp R of the lower unit L of signal S^C are both closed, and these lamps are therefore lighted so that signal S^C is displaying a caution indication. Lightout relay LOR^C is energized by virtue of the circuit for the lamp Y and with this relay energized, track relays TR^C and TR^B both energized, and distant relay DR^C deenergized, distant relay DR^B is supplied with current of reverse polarity, thus causing approach lighting relay ALR^C to be energized. The remaining lamps of signal S^C are all deenergized.

Distant relay DR^B being energized in its reverse direction and track relays TR^B and TR^A both being energized, distant relay DR^A is energized in its normal direction and approach lighting relay ALR^B is also energized. With relays DR^B and ALR^B both energized, the checking circuit for the lamp Y of signal S^B is closed and lightout relay LOR^B is, therefore, held energized. All circuits for the lamps of both units of signal S^B are open and this signal is, therefore, dark.

All relays at location A are energized and all lamps of signal S^A are, therefore, deenergized. The checking circuit for lamp G of signal S^A is closed so that lightout relay LOR^A is effective to check the filament of this lamp.

I will now assume that the filament of lamp Y of signal S^D becomes broken while the parts are in the positions in which they are shown in the drawings, and that the train W subsequently departs from the section in which it is shown in the drawings. As long as the train remains in the section shown the broken lamp filament will have no effect on the remainder of the apparatus since all circuits for the lamp Y are then open, but as soon as the train departs from this section and thus causes track relay TR^D to pick up, the broken lamp filament will prevent the circuit which would normally become closed for lamp Y of signal S^D at front contact 137-137^a of track relay TR^D from closing, and as a result, lightout relay LOR^D will remain deenergized, and will thus

prevent approach lighting relay ALR^D and distant relay DR^C from becoming energized in the usual manner. It follows, therefore, that the upper red lamp R of signal S^D will become extinguished but the lower red lamp will remain lighted, thus causing this signal to continue to display what is usually regarded as a stop signal. Furthermore, since distant relay DR^C now occupies its deenergized position, signal S^C will continue to display a caution indication and the apparatus associated with signals S^B and S^A will remain in the condition shown. When the train departs from the second section in advance of section D, distant relay DR^D will, of course, pick up in its reverse direction, and will thus interrupt the circuit which was previously closed for the lower red lamp R of signal S^D , and will close another circuit for this lamp including front contact 130—130^a of distant relay DR^D , back contact 132 of approach lighting relay ALR^D , reverse contact 133—133^b of relay DR^D , and back contact 159—159^b of relay LOR^D . Furthermore, the picking up of distant relay DR^D in its reverse direction will complete a circuit for the upper red lamp R of signal S^D passing from the left-hand terminal of secondary winding 36 of transformer T^D through wire 48, front contact 47—47^a of power-off relay POR^D , wire 166, front contact 137—137^a of track relay TR^D , wire 167, front contact 139—139^a of distant relay DR^D , back contact 144—144^b of approach lighting relay ALR^D , back contact 185 of lightout relay LOR^D , wire 186, the filament of the upper lamp R of signal S^D , wire 175, front contact 38—38^a of power-off relay POR^D , and wire 37 to the other terminal of the secondary winding 36 of transformer T^D . Signal S^D will, therefore, now display a full stop aspect. The picking up of distant relay DR^D in its reverse direction will have no effect on distant relay DR^C and signals S^C , S^B and S^A and the associated apparatus will, therefore, remain in the positions shown. When the train departs from the third section in advance of section C—D, distant relay DR^D will become energized in its normal direction and will close its normal polar contacts. The opening of the reverse polar contacts of relay DR^D will interrupt the circuit which was previously closed for the lower red lamp R of signal S^D but the closing of normal polar contact 133—133^a of relay DR^D will complete another circuit for this lamp, and this lamp will, therefore, remain lighted. The circuit for the upper red lamp of signal S^D will not be affected by the reversal of the polar contacts of relay DR^D , and signal S^D will, therefore, continue to display its stop aspect. Furthermore, the apparatus associated with signals S^C , S^B and S^A will remain in the position shown. It follows, therefore, that if a following train traverses the stretch of track shown in the drawings at any time after the filament of the yellow lamp Y of signal S^D becomes burned out or broken, the signals in the rear of signal S^D will display the same indications which these signals would have displayed if signal S^D had been caused to display its stop indication due to the presence of a train in the block to the left of point D.

I will now assume that with the parts in the positions in which they are shown in the drawings, the filament of the upper lamp G of signal S^D becomes burned out, and that the train W subsequently departs from the section to the left of point D. Under these conditions, the apparatus will function in the same manner as it normally functions until the train reaches the position in

which the checking circuit for the lamp G would normally become closed, whereupon lightout relay LOR^D will become deenergized. When the lightout relay becomes deenergized it will interrupt the circuit which was previously closed for distant relay DR^C , and will thus cause this relay and approach lighting relay ALR^D to become deenergized. With distant relay DR^D energized in its normal direction, as will then be the case, the deenergization of approach lighting relay ALR^D will cause the upper and lower red lamps of signal S^D to both become energized and signal S^D will then display a stop aspect. Furthermore, the deenergization of distant relay DR^C caused by the deenergization of lightout relay LOR^D will cause signal S^C to display a caution indication, and will condition the apparatus associated with signal S^B to cause this signal to display an approach restricting indication if a train subsequently approaches this signal.

I will next assume that the parts are in the positions in which they are shown in the drawings, and that the yellow lamp Y of signal S^C becomes burned out. The burning out of this lamp will deenergize lightout relay LOR^C and will thus cause distant relay DR^B and approach lighting relay ALR^C to become energized. As a result, the lower red lamp of signal S^C will remain lighted by virtue of the circuit which was previously closed for this lamp, and the yellow lamp Y of signal S^C will become lighted to cause this latter signal to display a caution aspect. Furthermore, the deenergization of distant relay DR^B will reverse the polarity of the current supplied to distant relay DR^A so that if a train subsequently approaches signal S^A this signal will display an approach restricting aspect.

If, with the parts in the positions in which they are shown in the drawings the filament of the yellow lamp of signal S^B becomes burned out or broken, it will interrupt the checking circuit for the lamp, and will thus cause lightout relay LOR^B to become deenergized. The deenergization of this relay under these conditions will cause signal S^B to display a stop aspect and signal S^A to display a caution aspect in an obvious manner. Furthermore, the resultant deenergization of distant relay DR^A will cause the distant relay for the signal next in rear of signal S^A to be supplied with current of reverse polarity so that this latter signal will display an approach restricting aspect if a train subsequently approaches it.

I will next assume that with the parts in the positions in which they are shown in the drawings, the filament of the upper green lamp G of signal S^A becomes broken. The breaking of this filament will interrupt the checking circuit which was previously closed including this filament, and lightout relay LOR^A will, therefore, become deenergized and will thus deenergize approach lighting relay ALR^A and the distant relay for the signal next in rear of signal S^A . The deenergization of approach lighting relay ALR^A will cause signal S^A to display a stop aspect, while the deenergization of the distant relay for the signal next in rear of signal S^A will cause this latter signal to display a caution aspect, and will reverse the polarity of the current supplied to the distant relay for the second signal in rear of signal S^A . The signal second in rear of signal S^A will, therefore, be caused to display a caution aspect if a train subsequently approaches this signal.

Referring now to Fig. 7, the apparatus here shown is similar to that shown at location A in Fig. 6^a with the exception that the checking circuits for the upper green lamp G of signal S^A and the yellow lamp Y of this signal have been modified to include a full-wave rectifier R_{1A}, thus making it possible to decrease the number of contacts which are required on approach lighting relay ALR^A and on distant relay DRA. As shown in Fig. 7, the checking circuit for the upper lamp G of signal S^A normally passes from the left-hand terminal of the secondary winding 36 of transformer T^A through wire 48, front contact 47-47^a of power-off relay POR^A, wire 166, front contact 137-137^a of track relay TR^A, wire 167, front contact 139-139^a of distant relay DR^A, wire 199, rectifier R_{1A}, winding 9 of lightout relay LOR^A, rectifier R_{1A}, wire 191, front contact 141-141^a of approach lighting relay ALR^A, normal polar contact 142-142^a of distant relay DR^A, wire 168, the filament of lamp G, wire 169, the winding 18 of lightout relay LOR^A connected in multiple with asymmetric unit R^A, wire 170, front contact 38-38^a of power-off relay POR^A, and wire 37 to the other terminal of the secondary winding 36 of transformer T^A. When power-off relay POR^A is deenergized, this circuit is then supplied with direct current from battery E^A in an obvious manner. The checking circuit for the yellow lamp Y of signal S^A is similar to the checking circuit just traced for the upper lamp G of this signal with the exception that this latter circuit includes in place of normal polar contact 142-142^a of distant relay DR^A, wire 168 and the filament of lamp G, reverse polar contact 142-142^b of distant relay DR^A, wires 176 and 177, and the filament of lamp Y.

With the system constructed as shown in Fig. 7, it will be apparent that when either the checking circuit for lamp G or the checking circuit for lamp Y is closed, lightout relay LOR^A will be energized regardless of whether power-off relay POR^A is then picked up, so that the then-closed circuit is supplied with alternating current, or is released so that the then-closed circuit is supplied with direct current from battery E^A. It will also be obvious that the reason why lightout relay LOR^A will be energized when this circuit is supplied with alternating current is because the rectifier R_{1A} will rectify the current which is supplied to the lightout relay. It will further be obvious that, if desired, the apparatus at each of the other signal locations in Figs. 6 and 6^a may be modified in the same manner that the apparatus shown at location A in Fig. 7 is modified. The operation of the apparatus, as a whole, when modified in the manner shown in Fig. 7, is similar in all respects to that shown in Figs. 6 and 6^a and the operation of this apparatus need not, therefore, be repeated.

Although I have herein shown and described only a few forms of railway signaling systems embodying my invention, it is understood that various changes and modifications may be made therein within the scope of the appended claims without departing from the spirit and scope of my invention.

Having thus described my invention, what I claim is:

1. In combination, a stretch of railway track divided into blocks, a relay associated with each block, a signal for each block controlled in part by the associated relay and by traffic conditions in advance and including a lamp which becomes lighted to cause the signal to display an indica-

tion, means for lighting each lamp when and only when the block immediately in advance or immediately in rear of the associated signal is occupied, and means for energizing each relay at all times when the filament of the associated lamp is intact. 5

2. In combination, a stretch of railway track divided into blocks, a two winding relay associated with each block, a signal for each block controlled by traffic conditions in advance and 10 also by the associated relay in such manner that the mechanism of said signal will occupy its stop position when the associated relay is deenergized, each said signal being provided with a lamp which at times becomes lighted to cause the signal to display an indication, an energizing circuit for each lamp controlled by traffic conditions in rear of the associated signal and including one winding of the associated relay, and a checking circuit for the lamp closed whenever the 15 energizing circuit is open and including the other winding of the associated relay, the parts being so proportioned that each relay will be energized whenever either the energizing or the checking circuit for the associated lamp is closed. 25

3. In combination, a stretch of railway track divided into blocks, a lightout relay for each block; a signal for each block having stop, caution and proceed positions and controlled by traffic conditions in advance and also by the associated relay in such manner that the signal is prevented from moving to its caution or proceed position unless the associated relay is energized, each said signal being provided with a lamp which becomes lighted to cause the signal to display an indication; means for lighting each lamp when and only when the block immediately in advance or immediately in rear of the associated signal is occupied, and means controlled by each lamp for controlling the associated lightout relay in such manner that the relay will be energized at all times except when the filament of the lamp is burned out or broken. 30

4. In combination, a stretch of railway track divided into blocks, a lightout relay for each block; a signal for said block having stop, caution and proceed positions and controlled by traffic conditions in advance and also by the associated relay in such manner that the signal is prevented from moving to its caution or proceed position unless the associated relay is energized, each said signal being provided with a lamp which becomes lighted to cause the signal to display an indication; means for lighting each lamp when and only when the block immediately in advance or immediately in rear of the associated signal is occupied, and a circuit for each lamp including a winding of the associated lightout relay and controlled by traffic conditions in rear of the associated signal. 45

5. In combination, a stretch of railway track divided into blocks, a two-winding relay for each block, a signal for each block having stop, caution and proceed positions and controlled by traffic conditions in advance and also by the associated two-winding relay in such manner that the signal is prevented from moving to its caution or proceed position unless the associated two-winding relay is energized, each said signal being provided with a lamp which at times becomes lighted to cause the signal to display an indication, an approach lighting relay associated with each signal and controlled by traffic conditions in rear of the associated signal, a checking circuit for each lamp including the one winding 50

- of the associated two-winding relay, and an energizing circuit for each lamp controlled by the associated approach lighting relay and including the other winding of the associated two-winding relay, the parts being so proportioned that each lamp will be lighted when and only when the associated energizing circuit is closed but that each two-winding relay will be energized whenever either the energizing circuit or the checking circuit for the associated lamp is closed.
6. In combination, a stretch of railway track divided into blocks, a two-winding relay for each block, a signal for each block having stop, caution and proceed positions and controlled by traffic conditions in advance and also by the associated two-winding relay in such manner that the signal is prevented from moving to its caution or proceed position unless the associated two-winding relay is energized, each said signal being provided with a lamp which at times becomes lighted to cause the signal to display an indication, an approach lighting relay associated with each signal and controlled by traffic conditions in rear of the associated signal, a signal repeater relay associated with each signal, means for energizing each signal repeater relay when the associated signal occupies either its caution or its proceed position, a checking circuit for each lamp including the one winding of the associated two-winding relay, and an energizing circuit for each lamp controlled by the associated approach lighting and signal repeater relays and including the other winding of the associated two-winding relay, the parts being so proportioned that each lamp will be lighted when and only when the associated energizing circuit is closed but that each two-winding relay will be energized whenever either the energizing circuit or the checking circuit for the associated lamp is closed.
7. In combination, a stretch of railway track divided into blocks, a two-winding relay for each block, a signal for each block having stop, caution and proceed positions and controlled by traffic conditions in advance and also by the associated two-winding relay in such manner that the signal is prevented from moving to its caution or proceed position unless the associated two-winding relay is energized, each said signal being provided with a lamp which at times becomes lighted to cause the signal to display an indication, an approach lighting relay associated with each signal and controlled by traffic conditions in rear of the associated signal, a signal repeater relay associated with each signal, means for energizing each signal repeater relay when the associated signal occupies either its caution or its proceed position, a checking circuit for each lamp including the one winding of the associated two-winding relay; and an energizing circuit for each lamp including the other winding of the associated two-winding relay and a back contact of the associated approach lighting relay connected in multiple with a back contact of the associated signal repeater relay, the parts being so proportioned that each lamp will be lighted when and only when the associated energizing circuit is closed but that each two-winding relay will be energized whenever either the energizing circuit or the checking circuit for the associated lamp is closed.
8. In combination, a stretch of railway track divided into blocks, a two-winding relay for each block, a signal for each block having stop, caution and proceed positions and including a lamp which is lighted when the signal is displaying an indication, means for controlling each signal controlled by traffic conditions in advance and also by the associated two-winding relay in such manner that the signal is prevented from displaying either a caution or a proceed indication unless the associated two-winding relay is energized, a checking circuit for each lamp including both windings of the associated two-winding relay and closed at all times when the block immediately in advance and immediately in rear of the signal are unoccupied provided the lamp filament is then intact, and an energizing circuit for each lamp including one winding only of the associated two-winding relay and closed only when the block immediately in advance or immediately in rear of the associated signal is occupied, the parts being so proportioned that each two-winding relay will be energized when either the energizing circuit or checking circuit for the associated lamp is closed.
9. In combination, a stretch of railway track divided into blocks, a two-winding relay for each block, a signal for each block having stop, caution and proceed positions and including a lamp which is lighted when the signal is displaying an indication, means for controlling each signal controlled by traffic conditions in advance and also by the associated two-winding relay in such manner that the signal is prevented from displaying either a caution or a proceed indication unless the associated two-winding relay is energized, a checking circuit for each lamp including both windings of the associated two-winding relay and closed at all times when the block immediately in advance and the block immediately in rear of the signal are unoccupied provided the lamp filament is then intact, and an energizing circuit for each lamp including one winding only of the associated two-winding relay and closed only when the block immediately in advance or immediately in rear of the associated signal is occupied, the parts being so proportioned that each two-winding relay will be energized when either the energizing circuit or checking circuit for the associated lamp is closed.
10. In combination, a stretch of railway track divided into blocks, a two-winding relay for each block, a signal for each block having stop, caution and proceed positions and including a lamp which is lighted when the signal is displaying an indication, means for controlling each signal controlled by traffic conditions in advance and also by the associated two-winding relay in such manner that the signal is prevented from displaying either a caution or a proceed indication unless the associated two-winding relay is energized, a checking circuit for each lamp including both windings of the associated two-winding relay and arranged to be closed at all times when the block immediately in advance and immediately in rear of the signal is unoccupied provided the lamp filament is then intact, an energizing circuit for each lamp including one winding only of the associated two-winding relay and closed only when the block immediately in advance or immediately in rear of the associated signal is occupied, and an asymmetric unit connected in multiple with said one winding of each two-winding relay to cause each two-winding relay to become energized when the energizing circuit for the associated lamp is closed.

regardless of whether the energizing circuit is supplied with direct or alternating current.

11. In combination, a stretch of railway track divided into blocks, a two-winding relay for each block, a signal for each block having stop, caution and proceed positions and including a lamp which is lighted when the signal is displaying an indication, means for controlling each signal controlled by traffic conditions in advance and also by the associated two-winding relay in such manner that the signal is prevented from displaying either a caution or a proceed indication unless the associated two-winding relay is energized, a slow releasing signal repeater relay associated with each signal, means for energizing each signal repeater relay whenever the associated signal occupies either its caution or its proceed position, an approach lighting relay associated with each signal and arranged to become deenergized when a train approaches the signal, a checking circuit for each lamp controlled by the associated signal repeater and approach lighting relays and including both windings of the associated two-winding relay connected in series, and an energizing circuit for each signal lamp controlled by the associated approach lighting relay and including one winding only of the associated two-winding relay, the parts being so proportioned that each lamp will become lighted when and only when the energizing circuit for the lamp is closed but that each two-winding relay will be energized whenever either the energizing or the checking circuit for the associated lamp is closed.
12. In combination, a stretch of railway track divided into blocks, a two-winding relay for each block, a signal for each block having stop, caution and proceed positions and including a lamp which is lighted when the signal is displaying an indication, means for controlling each signal controlled by traffic conditions in advance and also by the associated two-winding relay in such manner that the signal is prevented from displaying either a caution or a proceed indication unless the associated two-winding relay is energized, a slow releasing signal repeater relay associated with each signal, means for energizing each signal repeater relay whenever the associated signal occupies either its caution or its proceed position, an approach lighting relay associated with each signal and arranged to become deenergized when a train approaches the signal, a checking circuit for each lamp controlled by the associated signal repeater and approach lighting relays and including both windings of the associated two-winding relay connected in series, a first energizing circuit for each signal lamp controlled in part by the associated approach lighting relay and including one winding only of the associated two-winding relay, and a second energizing circuit for each signal lamp controlled in part by the associated signal repeater relay and including said one winding only of the associated two-winding relay, the parts being so proportioned that each lamp will become lighted when and only when one or the other of the energizing circuits for the lamp is closed but that each two-winding relay will be energized whenever either the energizing or the checking circuit for the associated lamp is closed.
13. In combination, a stretch of railway track divided into blocks, a two-winding relay for each block, a signal for each block having stop, caution and proceed positions, and including a lamp which is lighted when the signal is displaying an

indication, means for controlling each signal controlled by traffic conditions in advance and also by the associated two-winding relay in such manner that the signal is prevented from displaying either a caution or a proceed indication unless the associated two-winding relay is energized, a slow releasing signal repeater relay associated with each signal, means for energizing each signal repeater relay whenever the associated signal occupies either its caution or its proceed position, an approach lighting relay associated with each signal and arranged to become deenergized when a train approaches the signal; a checking circuit for each signal lamp including a front contact of the associated approach lighting relay, a front contact of the associated signal repeater relay, and both windings in series of the associated two-winding relay; a first energizing circuit for each lamp including a back contact of the associated approach lighting relay and one winding only of the associated two-winding relay, and a second energizing circuit for each lamp including a back contact of the associated signal repeater relay and one winding only of the associated two-winding relay, the parts being so proportioned that each lamp will become lighted when and only when one or the other of the energizing circuits for the lamp is closed but that each two winding relay will be energized whenever either the energizing or the checking circuit for the associated lamp is closed.

14. In combination, a stretch of railway track divided into blocks, a signal for governing the entrance of traffic into each block including a winding and a lamp and responsive to reversals in the polarity of the current supplied to the winding, a track circuit for each block including a track relay, a slow-releasing signal repeater relay for each signal energized whenever the winding of the associated signal is energized, a lightout relay for each signal having a low resistance winding and a high resistance winding; a polarized line circuit for each signal including the winding of the signal, a front contact of the associated lightout relay, a front contact of the associated track relay, pole-changing contacts of the signal repeater relay for the signal next in advance, and the winding of the approach lighting relay for the signal next in advance; a checking circuit for each lamp including a front contact of the associated approach lighting relay, a front contact of the associated signal repeater relay and the high and low resistance windings in series of the associated lightout relay; a first energizing circuit for each lamp including a back contact of the associated approach lighting relay and the low resistance winding of the associated lightout relay, and a second energizing circuit for each lamp including a back contact of the associated signal repeater relay and the low resistance winding of the associated lightout relay.

15. In combination, a stretch of railway track divided into blocks, a signal for governing the entrance of traffic into each block including a winding and a lamp and responsive to reversals in the polarity of the current supplied to the winding, a track circuit for each block including a track relay, a slow-releasing signal repeater relay for each signal energized whenever the winding of the associated signal is energized, a lightout relay for each signal having a low resistance winding and a high resistance winding; a polarized line circuit for each signal including the winding of the signal, a front contact of the associated lightout relay, a front contact of the associated track relay, pole-changing contacts of the signal repeater relay for the signal next in advance, and the winding of the approach lighting relay for the signal next in advance; a checking circuit for each lamp including a front contact of the associated approach lighting relay, a front contact of the associated signal repeater relay and the high and low resistance windings in series of the associated lightout relay; a first energizing circuit for each lamp including a back contact of the associated approach lighting relay and the low resistance winding of the associated lightout relay, and a second energizing circuit for each lamp including a back contact of the associated signal repeater relay and the low resistance winding of the associated lightout relay.

- contact of the associated track relay, pole-changing contacts of the signal repeater relay for the signal next in advance, and the winding of the approach lighting relay for the signal next in advance; a checking circuit for each lamp including a front contact of the associated approach lighting relay, a front contact of the associated signal repeater relay and the high and low resistance windings in series of the associated lightout relay; a first energizing circuit for each lamp including a back contact of the associated approach lighting relay and the low resistance winding of the associated lightout relay; and a second energizing circuit for each lamp including a back contact of the associated signal repeater relay and the low resistance winding of the associated lightout relay, a source of alternating current, a power-off relay energized except in the event of a failure of said source of alternating current, a source of direct current, means for supply said first and second energizing circuits with current for said source of alternating or said source of direct current according as said power-off relay is energized or deenergized, and an asymmetric unit connected in multiple with the low resistance winding of said lightout relay to make said lightout relay respond to either alternating or direct current.
16. In combination, a stretch of railway track divided into blocks, a signal for governing the entrance of traffic into each block comprising an upper and a lower signal mechanism each including an electric lamp and each responsive to the polarity of the current supplied thereto, each said signal being capable of displaying "stop" when the associated mechanisms are both deenergized, "caution" when the upper mechanism is supplied with current of reverse polarity and the lower mechanism is deenergized, "approach restricting" when the upper mechanism is supplied with current of reverse polarity and the lower mechanism is supplied with current of normal polarity, and "proceed" when the upper mechanism is supplied with current of normal polarity and the lower mechanism is deenergized; a lightout relay associated with each signal, means for normally supplying the upper mechanism of each signal with current of normal polarity when the next three blocks in advance are unoccupied and with current of reverse polarity when only one or two blocks next in advance are unoccupied, means for supplying the lower mechanism of each signal with current of normal polarity when and only when the associated lightout relay is energized, the two blocks next in advance are unoccupied and the third block in advance is occupied, means for lighting the lamps associated with a signal when a train occupies the block next in rear or either one of the two blocks next in advance of the signal, and means for energizing the lightout relay associated with each signal at all times except when the filament of the lamp associated with the upper mechanism of the signal is burned out or broken.
17. In combination, a stretch of railway track divided into blocks, a signal for governing the entrance of traffic into each block comprising an upper and a lower signal mechanism each including an electric lamp and each responsive to the polarity of the current supplied thereto, each said signal being capable of displaying "stop" when the associated mechanisms are both deenergized, "caution" when the upper mechanism is supplied with current of reverse polarity and the lower mechanism is deenergized, "approach restricting" when the upper mechanism is supplied with current of reverse polarity and the lower mechanism is supplied with current of normal polarity, and "proceed" when the upper mechanism is supplied with current of normal polarity and the lower mechanism is deenergized; a two-winding lightout relay associated with each signal, means for normally supplying the upper mechanism of each signal with current of normal polarity when the three blocks next in advance are unoccupied and with current of reverse polarity when only one or two blocks next in advance are unoccupied, means for supplying the lower mechanism of each signal with current of normal polarity when and only when the associated lightout relay is energized, the two blocks next in advance are unoccupied and the third block in advance is occupied, means for lighting the lamps associated with a signal when a train occupies the block next in rear or either one of the two blocks next in advance of the signal, and means for energizing the lightout relay associated with each signal at all times except when the filament of the lamp associated with the upper mechanism of the signal is burned out or broken.
18. In combination, a stretch of railway track divided into blocks, a signal for governing the entrance of traffic into each block comprising an upper and a lower signal mechanism each including an electric lamp and each responsive to the polarity of the current supplied thereto, each said signal being capable of displaying "stop" when the associated mechanisms are both deenergized, "caution" when the upper mechanism is supplied with current of reverse polarity and the lower mechanism is deenergized, "approach restricting" when the upper mechanism is supplied with current of reverse polarity and the lower mechanism is supplied with current of normal polarity, and "proceed" when the upper mechanism is supplied with current of normal polarity and the lower mechanism is deenergized; a two-winding lightout relay associated with each signal, means for normally supplying the upper mechanism of each signal with current of normal polarity when the next three blocks in advance are unoccupied and with current of reverse polarity when only one or two blocks next in advance are unoccupied, means for supplying the lower mechanism of each signal with current of normal polarity when and only when the associated lightout relay is energized, the two blocks next in advance are unoccupied, and the third block next in advance is occupied, a slow releasing signal repeater relay associated with each signal, means for energizing each signal repeater relay when either the upper or the lower mechanism of the associated signal is energized with current of normal polarity, an approach lighting relay associated with each signal, means for energizing each approach lighting relay when the block next in advance and the block next in rear of the associated signal are both unoccupied, means for energizing the lamp for the upper mechanism of each signal when either the associated approach lighting relay or the associated signal repeater relay is deenergized, an energizing circuit for the lamp of the upper mechanism of each signal controlled by the associated ap-

- proach lighting and signal repeater relays and including one winding of the associated lightout relay, and a checking circuit for the lamp of the upper mechanism of each signal controlled by the associated approach lighting and signal repeater relays and including both windings of the associated lightout relay in series.
19. In combination, a stretch of railway track divided into blocks, a signal for governing the entrance of traffic into each block comprising an upper and a lower signal mechanism each including an electric lamp and each responsive to the polarity of the current supplied thereto, each said signal being capable of displaying "stop" when the associated mechanisms are both deenergized, "caution" when the upper mechanism is supplied with current of reverse polarity and the lower mechanism is deenergized, "approach restricting" when the upper mechanism is supplied with current of reverse polarity and the lower mechanism is supplied with current of normal polarity, and "proceed" when the upper mechanism is supplied with current of normal polarity and the lower mechanism is deenergized; a two winding lightout relay associated with each signal, means for normally supplying the upper mechanism of each signal with current of normal polarity when the next three blocks in advance are unoccupied and with current of reverse polarity when only one or two blocks next in advance are unoccupied; means for supplying the lower mechanism of each signal with current of normal polarity when the associated lightout relay is energized, the two blocks next in advance are unoccupied, and the third block in advance is occupied; means for lighting the lamps associated with a signal when a train occupies the block next in rear or either one of the two blocks next in advance of the signal; and means for energizing the lightout relay associated with each signal at all times except when the filament of the lamp associated with the upper mechanism of the signal is burned out or broken.
20. In combination, a stretch of railway track divided into blocks, a signal for governing the entrance of traffic into each block comprising an upper and a lower signal mechanism each including an electric lamp and each responsive to the polarity of the current supplied thereto, each said signal being capable of displaying "stop" when the associated mechanisms are both deenergized, "caution" when the upper mechanism is supplied with current of reverse polarity and the lower mechanism is supplied with current of normal polarity, and "proceed" when the upper mechanism is supplied with current of normal polarity and the lower mechanism is deenergized; a two winding lightout relay associated with each signal, means for normally supplying the upper mechanism of each signal with current of normal polarity when the next three blocks in advance are unoccupied and with current of reverse polarity when only one or two blocks next in advance are unoccupied; means for supplying the lower mechanism of each signal with current of normal polarity when the associated lightout relay is energized, the two blocks next in advance are unoccupied, and the third block in advance is occupied; a slow releasing signal repeater relay associated with each signal, means for energizing each signal repeater relay when either the upper or the lower mechanism of the associated signal is energized with current of normal polarity, an approach lighting relay associated with each signal, means for energizing each approach lighting relay when the block next in advance and the block next in rear of the associated signal are both unoccupied, means for energizing the lamp for the upper mechanism of each signal when either the associated approach lighting relay or the associated signal repeater relay is deenergized, a first energizing circuit for the upper lamp of each signal including a back contact of the associated approach lighting relay, a front contact of the associated signal repeater relay, and one winding of the associated lightout relay; a second energizing circuit for the upper lamp of each signal including a back contact of the associated signal repeater relay and said one winding of the associated lightout relay; and a checking circuit for the upper lamp of each signal including a front contact of the associated approach lighting relay, a front contact of the associated signal repeater relay, and both windings of the associated lightout relay in series.
20. In combination, a stretch of railway track divided into blocks, a signal for governing the entrance of traffic into each block comprising an upper and a lower signal mechanism each including an electric lamp and each responsive to the polarity of the current supplied thereto, each said signal being capable of displaying "stop" when the associated mechanisms are both deenergized, "caution" when the upper mechanism is supplied with current of reverse polarity and the lower mechanism is deenergized, "approach restricting" when the upper mechanism is sup-

plied with current of reverse polarity and the lower mechanism is supplied with current of normal polarity, and "proceed" when the upper mechanism is supplied with current of normal polarity and the lower mechanism is deenergized; a lightout relay associated with each signal, means for supplying the upper mechanism with current of normal polarity when the associated lightout relay is energized and the next three blocks in advance are unoccupied and with current of reverse polarity when the associated lightout relay is energized and only one or two blocks next in advance are unoccupied; means for supplying the lower mechanism of each signal with current of normal polarity when the two blocks next in advance are unoccupied, and the third block in advance is occupied; means for lighting the lamps associated with a signal when a train occupies the block next in rear or either one of the two blocks next in advance of the signal; and means for energizing the lightout relay associated with each signal at all times except when the filament of the lamp associated with the upper mechanism of the signal is burned out or broken.

21. In combination, a stretch of railway track divided into blocks, a signal for governing the entrance of traffic into each block comprising an upper and a lower signal mechanism each including an electric lamp and each responsive to the polarity of the current supplied thereto, each said signal being capable of displaying "stop" when the associated mechanisms are both deenergized, "caution" when the upper mechanism is supplied with current of reverse polarity and the lower mechanism is deenergized, "approach restricting" when the upper mechanism is supplied with current of reverse polarity and the lower mechanism is supplied with current of normal polarity, and "proceed" when the upper mechanism is supplied with current of normal polarity and the lower mechanism is deenergized; a two-winding lightout relay associated with each signal, means for normally supplying the upper mechanism of each signal with current of normal polarity when the next three blocks in advance are unoccupied and with current of reverse polarity when only one or two blocks next in advance are unoccupied, means for supplying the lower mechanism of each signal with current of normal polarity when and only when the associated lightout relay is energized, the two blocks next in advance are unoccupied, and the third block in advance is occupied, means for lighting the lamps associated with a signal when a train occupies the block next in rear or either one of the two blocks next in advance of the signal, means for supplying the one winding of each lightout relay with energizing current whenever the upper lamp of the associated signal is lighted, and a checking circuit for the upper lamp of each signal closed at all times except when the lamp is lighted and including both windings of the associated approach lighting relay in series.

22. In combination, a stretch of railway track divided into blocks, a signal for governing the entrance of traffic into each block comprising an upper and a lower signal mechanism each including an electric lamp and each responsive to the polarity of the current supplied thereto, each said signal being capable of displaying "stop" when the associated mechanisms are both deenergized, "caution" when the upper mechanism is supplied with current of reverse polarity and the lower mechanism is deenergized, "approach restricting" when the upper mechanism is sup-

lower mechanism is deenergized, "approach restricting" when the upper mechanism is supplied with current of reverse polarity and the lower mechanism is supplied with current of normal polarity, and "proceed" when the upper mechanism is supplied with current of normal polarity and the lower mechanism is deenergized; a two winding lightout relay associated with each signal, means for supplying the upper mechanism of each signal with current of normal polarity when the associated lightout relay is energized and the next three blocks in advance are unoccupied and with current of reverse polarity when the associated lightout relay is energized and only one or two blocks next in advance are unoccupied; means for supplying the lower mechanism of each signal with current of normal polarity when and only when the two blocks next in advance are unoccupied, and the third block in advance is occupied; a slow releasing signal repeater relay associated with each signal, means for energizing each signal repeater relay when either the upper or the lower mechanism of the associated signal is energized with current of normal polarity, an approach lighting relay associated with each signal, means for energizing each approach lighting relay when and only when the two blocks next in advance and the block next in rear of the associated signal are all unoccupied, means for energizing the lamp for the lower mechanism of each signal when either the associated approach lighting relay or the associated signal repeater relay is deenergized; an energizing circuit for the lamp of the upper mechanism of each signal controlled by the associated approach lighting and signal repeater relays and including one winding of the associated lightout relay, and a checking circuit for the lamp of the upper mechanism of each signal controlled by the associated approach lighting and signal repeater relays and including both windings of the associated lightout relay in series.

23. In combination, a stretch of railway track divided into blocks, a signal for governing the entrance of traffic into each block comprising two signal mechanisms each including an electric lamp which is lighted when the signal is displaying an indication, each said signal being capable of indicating stop, caution, approach restricting, and proceed, a two-winding lightout relay associated with each signal, means controlled by traffic conditions in advance for controlling the one mechanism of each signal, means controlled by traffic conditions in advance and by the associated lightout relay for controlling the other mechanism of each signal, an energizing circuit for the lamp of the one mechanism of each signal controlled by traffic conditions in rear and including one winding of the associated lightout relay, a checking circuit for the lamp of the one mechanism of each signal including the other winding of the associated relay and arranged to be closed whenever the energizing circuit is open, the parts being so proportioned that when either the energizing circuit or the checking circuit for a lamp is closed the associated lightout relay will be energized, and means controlled by traffic conditions in rear of each signal for energizing the lamp of the other mechanism of the signal.

24. In combination, a stretch of railway track divided into blocks, a signal for governing the entrance of traffic into each block comprising two signal mechanisms each including an electric lamp which is lighted when the signal is displaying an indication, each said signal being ca-

pable of indicating stop, caution, approach restricting, and proceed, a two-winding lightout relay associated with each signal, means controlled by the associated lightout relay and by traffic conditions in advance for controlling both mechanisms of each signal, an energizing circuit for the lamp of the one mechanism of each signal controlled by traffic conditions in rear and including one winding of the associated lightout relay, a checking circuit for the lamp of the one mechanism of each signal including the other winding of the associated relay and arranged to be closed whenever the energizing circuit is open, the parts being so proportioned that when either the energizing circuit or the checking circuit for a lamp is closed the associated lightout relay will be energized, and means controlled by traffic conditions in rear of each signal for energizing the lamp of the other mechanism of the signal.

25. In combination, a stretch of railway track divided into blocks, a signal for governing the entrance of traffic into each block comprising an upper and a lower signal mechanism each including an electric lamp and each responsive to the polarity of the current supplied thereto, each said signal being capable of displaying "stop" when the associated mechanisms are both deenergized, "caution" when the upper mechanism is supplied with current of reverse polarity and the lower mechanism is deenergized, "approach restricting" when the upper mechanism is supplied with current of reverse polarity and the lower mechanism is deenergized; a two winding lightout relay associated with each signal, means for supplying the upper mechanism with current of normal polarity when the associated lightout relay is energized and the next three blocks in advance are unoccupied and with current of reverse polarity when the associated lightout relay is energized and only one or two blocks next in advance are unoccupied, means for supplying the lower mechanism of each signal with current of normal polarity when and only when the two blocks next in advance and the block next in rear of the associated signal are all unoccupied, means for energizing the lamp for the lower mechanism of each signal when either the associated approach lighting relay or the associated signal repeater relay is deenergized, a first energizing circuit for the upper lamp of each signal including a back contact of the associated approach lighting relay, a front contact of the associated signal repeater relay, and one winding of the associated lightout relay, a second energizing circuit for the upper lamp of each signal including a back contact of the associated signal repeater relay and said one winding of the associated lightout relay; and a checking circuit for the upper lamp of each signal including a front contact of the associated approach lighting relay, a front contact of the associated signal repeater relay, 75

and both windings of the associated lightout relay in series.

26. In combination, a stretch of railway track divided into blocks, a relay associated with each block, a signal for each block controlled in part by the associated relay and by traffic conditions in advance and including a single light source comprising a filament which becomes incandescent when a train approaches the signal to cause the signal to display an indication, and means for energizing each relay at all times when the filament of the associated light source is intact.

27. In combination, a stretch of railway track divided into blocks, a signal for each block including a lamp which at times becomes lighted to cause the signal to display an indication, a lightout relay associated with each signal, a circuit for each signal effective for operating the signal only when the associated block is unoccupied and the associated lightout relay is energized, means controlled by traffic conditions in advance for controlling each circuit, means for lighting each lamp whenever the circuit for the signal next in rear is ineffective, and means for energizing each lightout relay at all times when the filament of the lamp for the associated signal is intact.

28. In combination, a stretch of railway track divided into blocks, a signal for each block responsive to the polarity of the current supplied thereto and including a lamp which at times becomes lighted to cause the signal to display an indication, a lightout relay associated with each signal, a polarized circuit for controlling each signal effective only when the associated block is unoccupied and the associated lightout relay is energized, means for controlling the polarity of each circuit in accordance with traffic conditions in advance, means for lighting each lamp whenever the circuit for the signal next in rear is ineffective, and means for energizing each lightout relay at all times when the filament of the lamp for the associated signal is intact.

29. In combination, a stretch of railway track divided into blocks, a signal capable of assuming proceed, caution or stop positions according as said signal is supplied with current of normal or reverse polarity or is deenergized and including a lamp which becomes lighted to cause the signal to display an indication, a lightout relay associated with each signal, a polarized circuit for controlling each signal closed only when the associated block is unoccupied and the associated lightout relay is energized, means for controlling the polarity of each circuit in accordance with traffic conditions in advance, means for lighting each lamp whenever the circuit for the signal next in rear is open, and means for energizing each lightout relay at all times when the filament of the lamp for the associated signal is intact.

30. In combination, a stretch of railway track divided into blocks, a signal capable of assuming proceed, caution or stop positions according as said signal is supplied with current of normal or reverse polarity or is deenergized and including a lamp which becomes lighted to cause the signal to display an indication, a lightout relay associated with each signal, a polarized circuit for controlling each signal closed only when the associated block is unoccupied and the associated lightout relay is energized, means for controlling the polarity of each circuit in accordance with traffic conditions in advance, an approach lighting relay for each signal included in the circuit for the signal next in rear, means for energizing each signal lamp whenever the associated ap-

proach lighting relay is deenergized, and means for energizing each lightout relay at all times when the filament of the lamp for the associated signal is intact.

31. In combination, a stretch of railway track divided into blocks, a signal capable of assuming proceed, caution or stop positions according as said signal is supplied with current of normal or reverse polarity or is deenergized and including a lamp which becomes lighted to cause the signal to display an indication, a lightout relay associated with each signal, a signal repeater relay associated with each signal and arranged to be energized whenever the associated signal occupies either its caution or proceed position, a polarized circuit for each signal controlled by the signal repeater relay for the signal next in advance and effective only when the associated block is unoccupied and the associated lightout relay is energized, means for lighting each lamp whenever the circuit for the signal next in rear is ineffective, and means for energizing each lightout relay at all times when the filament of the lamp for the associated signal is intact.

32. In combination, a stretch of railway track divided into blocks, a signal capable of assuming proceed, caution or stop positions according as said signal is supplied with current of normal or reverse polarity or is deenergized and including a lamp which becomes lighted to cause the signal to display an indication, a lightout relay associated with each signal, a signal repeater relay associated with each signal and arranged to be energized whenever the associated signal occupies either its caution or proceed position, a polarized circuit for each signal controlled by the signal repeater relay for the signal next in advance and closed only when the associated block is unoccupied and the associated lightout relay is energized, an approach lighting relay for each signal included in the circuit for the signal next in rear, means for energizing each signal lamp whenever the associated approach lighting relay is deenergized, and means for energizing each lightout relay at all times when the filament of the lamp for the associated signal is intact.

33. In combination with a section of railway track, a signal for said section including a lamp which becomes lighted to cause the signal to display an indication, a lightout relay for said signal, means for conditioning said signal to display a proceed indication when and only when said section is unoccupied and said lightout relay is energized, and means for energizing said lightout relay at all times when the filament of said lamp is intact.

34. In combination with a section of railway track, a signal for said section including a lamp which becomes lighted to cause the signal to display an indication, a lightout relay for said signal, means for conditioning said signal to display a proceed indication when and only when said section is unoccupied and said lightout relay is energized, approach lighting means for lighting said lamp, and means for energizing said lightout relay at all times when the filament of said lamp is intact.

35. In combination with a section of railway track, a signal for said section including a lamp which becomes lighted to cause the signal to display an indication, a lightout relay for said signal, means for conditioning said signal to display a proceed indication when and only when said section is unoccupied and said lightout relay

is energized, approach lighting means for lighting said lamp, means for energizing said lightout relay at all times when the filament of said lamp is intact, and means effective when said filament fails and said lightout relay becomes deenergized for causing a restrictive indication to be displayed for traffic entering the approach section to said signal.

36. In combination, a stretch of railway track divided to form a block, an approach energized signal for governing the entrance of traffic into said block and including a lamp which is lighted when the signal is displaying an indication, a two-winding lightout relay, means for energizing the one winding of said relay whenever said lamp is lighted, a checking circuit for said lamp including the other winding of said relay and closed whenever said lamp is extinguished but would be lighted if a train were approaching said signal and effective when closed for energizing said relay, and means for controlling said signal controlled by said relay.

37. In combination, a stretch of railway track divided to form a block, an approach energized signal for governing the entrance of traffic into said block and including a lamp which is lighted when the signal is displaying an indication, a two-winding lightout relay, means for energizing the one winding of said relay whenever said lamp is lighted, a checking circuit for said lamp including the other winding of said relay and closed whenever said lamp is extinguished but would be lighted if a train were approaching said signal, and means for causing said signal to display a restrictive indication whenever said relay is deenergized.

38. In combination, a stretch of railway track divided to form a block, an approach energized signal for said block controlled by traffic conditions in advance and including a lamp which is lighted when said signal is displaying an indication, means for passing a checking current through said lamp whenever said lamp is extinguished but would be lighted if a train were approaching said signal, a lightout relay, means for energizing said relay whenever current is being supplied to the filament of said lamp, and means controlled by said relay for controlling said signal.

39. In combination, a stretch of railway track divided to form a block, an approach energized signal for said block controlled by traffic conditions in advance and including a lamp which is lighted when said signal is displaying an indication, a two-winding lightout relay having one winding connected in series with the filament of said lamp whenever said lamp is lighted, a checking circuit for said lamp including the other winding of said relay and the filament of said lamp in series and arranged to be closed whenever said lamp is extinguished but would be lighted if a train were approaching said signal, and means for controlling said signal controlled by said lightout relay.

40. In combination, a stretch of railway track divided to form a block, a signal for said block capable of displaying a plurality of indications in accordance with traffic conditions in advance and including a lamp which is lighted when the signal is displaying an indication, means for normally causing said signal to display an indication when and only when a train is approaching said signal or occupies said block, a two-winding lightout relay, means for energizing the first winding of said relay whenever said lamp is lighted, means for energizing the other winding of said relay whenever traffic conditions in advance are such that said lamp would be lighted if a train were approaching said signal or occupied said block, and means controlled by said relay for causing said signal to display a stop indication if said relay becomes deenergized.

41. In combination, a stretch of railway track divided into blocks, a light signal for each block capable of providing a plurality of indications and including a lamp which is lighted when the signal is displaying an indication, means controlled by traffic conditions for normally causing each signal to display an indication in accordance with traffic conditions in advance when a train approaches the signal, means for passing a checking current through the filament of each lamp whenever the lamp is extinguished but traffic conditions in advance are such that the lamp would be lighted if a train were then approaching the signal, a lightout relay associated with each signal and supplied with current whenever the associated lamp is lighted or is receiving checking current, and means controlled by each relay for causing the associated signal to display a stop indication irrespective of traffic conditions if the relay becomes deenergized and the signals in rear of such signal to display the same indication when a train approaches them that they would display if such signal displayed its stop indication due to traffic conditions in advance.

42. In combination, a stretch of railway track divided into blocks, an approach energized signal for governing the entrance of traffic into each block and capable of displaying a plurality of indications and including a lamp which is lighted when the signal is displaying an indication, a two-winding relay associated with each signal, means for energizing the one winding of each relay whenever the lamp of the associated signal is lighted, a checking circuit for each lamp including the other winding of the associated relay and closed whenever the lamp is extinguished but would be lighted if a train were approaching the signal and effective when closed for energizing the associated relay, and means controlled by each relay and effective if the relay becomes deenergized to cause the associated signal and the signals in rear thereof to display the same indications when a train approaches them that they normally display when a train occupies the block next in advance of such associated signal.

PAUL H. CRAGO.
